FILLED CONTAINER CASER

Donald MacLeod, Milford, Ohio, assignor to Tech-Art, Inc., Milford, Ohio, a corporation of Ohio
Filed Dec. 11, 1959, Ser. No. 859,027
18 Claims. (Cl. 53—62)

This invention relates to improvements in a casing machine, that is a machine for loading filled milk containers of the impregnated cardboard carton variety into a case, basket or box and in which case, basket or box the said containers are delivered to retail dispensers and which

cases are utilized in the delivery of the containers to homes, retail outlets, and the like.

The present application discloses improvements in the construction and operation of the casing machine over the disclosure in the pending application of Donald MacLeod for Filled Container Casing, Serial Number 722,345 filed March 18, 1958, now U.S. Patent No. 2,975,569.

These cardboard containers, generally referred to as bottles, are made in a plurality of sizes to contain a half gallon, a quart, a pint and a half pint. The cardboard or carton containers are also made in a size between the half pint and pint, nominally designated as a third quart, for containing mixed drinks, such as chocolate milk, and which containers are adapted to have the contents shaken before consumption.

It is the practice to utilize the same size case for each of the sizes of cardboard containers above set forth with a case holding a full layer of half gallon or quart containers upstanding from the case bottom, two full layers of the third quart containers, a full layer and a partial layer of pints, said partial layer including one-half or three-quarter the number of containers forming a full layer, and half pints being, generally, disposed in three layers in the case and including two full layers and a third partial layer.

The caser of the present invention is adapted to be adjusted for automatically loading each case with the proper number of carton containers regardless of the size being cased.

It is the principal object of the present invention to provide a casing machine that automatically and expeditiously cases filled containers or cartons with the desired number thereof.

Another object of this invention is the provision of a casing machine which automatically, in effect, counts the number of filled containers in a case and upon reaching the desired number of filled containers in the case effects a repeat cycle.

It is also an object of this invention to provide, in conjunction with the caser, case conveying means which automatically positions a case with respect to the caser and prevents operation of the caser unless the case is properly positioned with respect to the caser.

It is a further and specific object of the present invention to provide a caser for casing filled carton type containers and which caser passes filled containers through various stages and positions between the receiving thereof and the casing thereof and which positions and operations are interlocked to prevent a subsequent operation prior to the completion of a previous operation.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

2

In the drawings:

FIG. 1 is a front elevational view of the casing machine of the present invention.

5 FIG. 2 is a side elevational view of the machine of FIG. 1 as seen particularly from the left hand side of said FIG. 1.

FIG. 3 is, in the main, a top plan view of the caser of the present invention with certain parts being shown in section as seen from line 3—3 on FIG. 2.

FIG. 4 is a fragmentary, sectional view through a portion of the machine as seen from line 4—4 on FIG. 3.

FIG. 5 is a view transversely of FIG. 4 as seen from line 5—5 on said FIG. 4.

15 FIG. 6 is a fragmentary, transverse, sectional view through the machine in a plane above that of FIG. 3 on FIG. 2 as seen from line 6—6 on said FIG. 2.

FIG. 7 is a diagrammatic view of the electric control circuit for effecting and controlling the operation of the machine.

20 FIG. 8 is a diagrammatic view of the hydraulic mechanism included in the operating mechanism of certain portions of the machine.

FIG. 9 is a diagrammatic view of the pneumatic control and actuating mechanism of certain parts of the machine.

25 FIG. 10 is a diagrammatic view of the motor control system and control current source for controlling and operating the machine.

FIG. 11 is a side elevational view of a carton container adapted to be cased by the machine of the present invention.

30 FIG. 12 is an end elevation of the container of FIG. 11.

FIG. 13 is a transverse, sectional view through the container as seen from line 13—13 on FIG. 11.

35 FIG. 14 is an enlarged, fragmentary, elevational and sectional view of the elevator adjusting means.

FIG. 15 is a view similar to FIG. 7 and is a diagrammatic view of a modified electric control circuit in the operating mechanism of certain portions of the machine.

40 Throughout the several views of the drawings similar reference characters are employed to denote the same or similar parts.

45 The machine of the present invention, as noted above, is for depositing a given number of filled paper containers of milk and the like into a box or basket generally referred to as a "case." The machine itself is generally referred to as a "caser" since it cases a number of said filled containers.

50 Briefly the container is made of cardboard formed of a single blank scored and folded to have a rectangle cross section as illustrated in FIGS. 11, 12 and 13.

55 As illustrated in said FIGS. 11, 12 and 13, the container comprises a bottom 20 from the edges of which upstand walls 21, at right angles to one another, to provide the said container with a transverse cross section rectangular in area. Two opposed of the walls are inwardly bent at their upper ends to be between the remaining two opposed walls, as illustrated at 22 and 23 in FIG. 11. The remaining two opposed walls extend for the full height of the container and incline toward one another with one of said walls having at its upper end a flap 24 folded over the upper end of the opposed wall and with the said overlapped members secured to one another as by a wire staple 25, as illustrated in FIG. 12. This construction is well known and the overlapped upper ends of the containers is referred to as a gable, indicated in the drawings by the reference numeral 26.

60 The said containers are each of a similar construction and are provided in a number of capacities such as half pint, third quart, full pint, quart and half gallon and which containers vary in area as well as in vertical height. 65 The chief variation in said containers is in height, in so far as the half pint, third quart, full pint and quarts are

concerned, and with said containers each having their side walls of the same width, while the half gallon container is not only of greater height but also has its walls of a greater width.

The boxes or cases into which the above containers are placed are identical in size and form and it is obvious that more individual containers of smaller capacity can be put into such a box or case than can the larger capacity containers. The customary practice is to put a single layer of half gallon and quart containers in a case to upstand from the bottom thereof, while with pints it is customary to put a full layer on the case bottom together with a half or three quarters layer of pints on top of the said full layer with said incomplete layer of pints tilting over while on top of the bottom layer, with third quart containers two full layers are placed in each case while with half pints there is generally added a third layer containing one half or three quarter the number of containers in a full layer. Regardless of the capacity of the individual containers in the cases no case is filled beyond its upper edge so that said cases may be stacked one on top of another.

The case filling machine or caser of the present invention is adapted to be adjusted for properly loading the cases with each of the above mentioned sizes of filled containers.

The caser or case filling machine of the present invention comprises a frame including spaced end uprights 27 and 28 which support laterally extending portions of the machine together with similarly spaced centrally located uprights 29 and 30. In order to adjust the vertical height of the machine as well as to dispose the operating tables of the machine in a horizontal plane, each of said uprights is provided at its lower end with a jack or leveling screw 31. The outer uprights are joined at their upper ends by means of a transverse member 32 and on which the afore-mentioned working tables are mounted.

The intermediate uprights 29 and 30 extend considerably above the transverse member 32 and provide the support for the actual casing or elevator mechanism as will presently be made clear. At one side, the left side, as seen in the drawings there is provided the means for bringing the filled containers to the machine and which means or mechanism comprises an endless conveyer 33 which extends either from a filling machine, not shown in the drawings as it forms no part of the present invention, or the said conveyer 33 extends from the filling machine discharge conveyer, and, again, which conveyer is not disclosed in the drawings. The loading conveyer 33, in effect a linked chain, is suitably supported by a frame-work including side members 34 and 35 which support at one end a shaft 36 having on its inner end a driving pulley or sprocket 37 for the said conveyer 33. Secured to the outer end of the shaft 36 is an actuating chain sprocket 38 about which is trained an endless sprocket chain 39. The chain 39, in turn, is trained about a sprocket 40 secured to a shaft 41 which forms part of a suitable speed reducer 42 connected with and driven by a shaft 43 of electric motor 44. The motor 44 is conveniently mounted on a platform 45 supported by the machine frame through suitable uprights 46 carried by the main frame elements 29, 30, and 32.

The conveyer chain 33 is illustrated as adapted to support and convey a row of containers to the casing machine and side rails 34 and 35 are arranged with respect to one another for properly and efficiently positioning said containers when they reach the discharge end of the conveyer 33 and which discharge end is at the end thereof at which the actuating drum or sprocket 37 is connected.

The discharge of the filled containers from the conveyer 33 is onto a supporting plate 47, which for convenience in description may be termed an accumulating platform, which is fixed and supported by the transverse frame member 32 or suitable supports carried thereby.

The said filled containers are moved on the said fixed table or platform 47 to a stop plate 48 upstanding from the said table 47 at its forward end, opposite to that of the conveyer 33.

5 Outwardly of the platform or table 47 and its end stop plate 48 there is provided a limit switch 49-50 mounted in position through appropriate supporting members including angle iron 51. The limit switch 49-50 is a commercial switch of the kind including two pairs 10 of contacts, of which one pair of contacts 49 are normally open while the second pair of contacts 50 are normally closed, see FIG. 7. The normally open contacts or switch 49 is closed by the filled containers when a full load, herein said full load of containers being four, are positioned on the accumulator platform or plate 47. Said switch or contacts are closed through an actuator 52 carried by the housing 53 of said switch 49-50 with said actuator 52 projecting through an aperture formed in the stop plate 48.

15 The contacts 50, normally closed, are simultaneously opened upon the closing of the contacts 49, and, as will subsequently be made clear, the switch or contacts 50 are in an alarm circuit operable to insure the proper functioning of the machine.

20 One side of the accumulator table 47 is provided by an upstanding plate 54 which actually is a pusher and has at its end nearest the conveyer 37 a fence 55. Substantially centrally of the pusher 54 it is connected through a clevis connection 56 with one end of a piston rod 57 25 which has at its other end a piston 58 disposed in a piston cylinder 59. The said cylinder 59 is suitably supported on framing mechanism supplied by the main frame and its transverse supporting mechanism and is believed amply clear from the drawings without a specific description 30 thereof.

35 The piston cylinder 59 has connected with its opposite ends, respectively, conduits 60 and 61 which, in turn, terminate in a valve housing 62. The valve housing 62 has disposed therein, see diagrammatic view, FIG. 8, 40 a valve sleeve 63 in which is disposed a spool type valve 64 having lands 65, 66 and 67 thereon with connecting circumferential grooves therebetween.

45 As shown in said FIG. 8 the valve sleeve 63 is provided with additional ports and with one of which ports one end of conduit 68 is connected with said conduit 68 having its other end connected with the outlet of an hydraulic pump 69. The said pump 69 has its inlet 50 connected by a conduit 70 with a sump or tank 71 containing an hydraulic medium. The pipe or conduit 68 has connected therewith a pressure regulating valve 72 to determine the working pressure in the system. Additional ports in the valve sleeve 63 has connected therewith one end of a discharge pipe or conduit 73 which terminates in the sump or tank 71.

55 As illustrated in FIG. 8 the valve 64 is positioned for connecting the hydraulic medium from the pump 69 with the conduit 61 and right hand end, as seen in FIG. 3, of the cylinder 59 for actuating the piston therein to the left and fully retracting the fence 55 and pusher 54 to the position thereof illustrated in said FIG. 3.

60 The valve 64 has extending from one side thereof a valve stem 74 which acts as the core of an electromagnetic solenoid coil 75, disposed within a housing connected to the valve housing 62 while the said valve 64 has extending from its other side a similar valve stem 76 likewise forming the core of an electromagnetic solenoid coil 77. The said valve and its operating solenoids are commercially obtainable items and are believed to be well known, it is to be remembered that the energization of either one causes a corresponding shift in the valve 64 and a subsequent operation of the piston controlled thereby. Each of the said electromagnetic solenoids is under the control of a switch as will presently be made clear.

70 75 As is obvious, the caser of the present invention is

electrically and hydraulically actuated and the electric control circuit is diagrammatically illustrated with accepted electrical symbols in FIG. 7. The operation of which along with the mechanisms controlled thereby will be described in the sequence of describing a complete cycle of the machine. Assuming, as we did above, that the filling machine is in operation for successively filling containers and which are closed or sealed after being filled, as shown in FIGS. 11 and 12, and the said filled containers delivered in a substantially continuous stream from the loading conveyor 33 to the accumulating table 47, and that when the limit switch contacts 49 are closed the following operation takes place.

As seen in FIG. 7 and assuming for the moment that the right and left hand vertical lines are electric wires or conductors 78 and 79 and are connected with an electric current source of appropriate voltage to operate the control mechanism, such voltage will generally be of approximately 110 volts A.C. Assuming that the circuit is otherwise in order, and, as will be noted, from FIG. 7, that one side of limit switch 49 has extending therefrom a wire 80 that terminates in the current source wire 78 with said wire 80 including normally closed relay switch contact 81 controlled by a relay switch solenoid to be subsequently pointed out. The other side of said limit switch 49 has connected therewith a wire 82 terminating in one side of a normally open limit switch 83. At this time the said limit switch 83 is closed, as follows:

The normally open limit switch 83 is located adjacent, what may be termed, a carriage 84 and onto which the filled containers are transferred by the pusher 54 from the accumulator table 47, as will presently be made clear, and said carriage 84 is presently in its retracted position wherefore the said normally open limit switch 83 is now closed.

As seen in said FIG. 7 said limit switch 83 has its other side connected with the other current feed wire 79, said connection being by way of a wire 85 that includes a solenoid coil 86 of a relay switch. The solenoid coil 86 controls a movable switch member 87 operable between fixed switch contacts 88 and 89. The movable switch member 87 is normally closed with the switch contact 88 and is connected with the switch contact 89, after being disconnected from its switch contact 88, upon the energization of the relay switch solenoid coil 86.

From the foregoing it will be noted that the accumulation of a full load of filled containers on the accumulator table 47 closes the limit switch 49 and completes an electric circuit for energizing relay switch solenoid coil 86 and actuates movable switch member 87. The movable switch member 87 is connected through a wire 90 with the control circuit current feed wire 78 while the engageable or fixed contacts 88 and 89 are respectively connected by wires 91 and 92 with the other control circuit current feed wire 79. The circuit wire 92 includes the electromagnetic solenoid coil 77 while the circuit wire 91 includes the electromagnetic solenoid 75 of the valve 64.

The energization of the relay switch solenoid coil 86 closes the circuit including the normally open switch contact 89 and thereby completes an electric circuit through the hydraulic valve actuating solenoid 77. As seen in FIG. 8 the energization of the solenoid 77 shifts the valve 64 for thereby connecting the hydraulic pump pressure conduit 68 with the conduit 66 to the outer or left hand end of the cylinder 59, as seen in FIGS. 1 and 3, for actuating the piston 58 therein to the right. This actuation of the piston 58 carries with it the pusher 54 for shifting the accumulated filled containers on the accumulator table 47 onto the aforementioned carriage 84.

It should be noted that the parts are so designed that the accumulated filled containers on the table 47, regardless of the capacity of said containers, are completely and fully shifted onto the carriage 84.

For the purpose of insuring proper movement of the

pusher 54 it has projecting from its rear surface one or more guide bars, two being shown, 93 and 94, which, respectively pass through a guide block 95 and 96 carried by and upstanding from a portion of the machine frame.

5 For convenience, the guide block 96 is taken advantage of to support a limit switch 97 including an actuating arm 98. The actuating arm 98 of the limit switch 97 is adapted to be engaged and operated by an abutment 99 conveniently carried by guide bar 94 through an arm 100 secured to said guide bar 94. The said limit switch is operated when the pusher 54 has fully and completely transferred the filled containers from the accumulator table 47 to the carriage 84.

The limit switch 97 as shown in FIG. 7 is a normally closed switch and has one side thereof connected by a wire 101 with the current supply or feed wire 78. The other side of said limit switch 97 has connected therewith one end of a wire 102 that terminates in a movable switch member 103 which is substantially similar to the movable switch member 87 and is movable between fixed switch contacts 104 and 105. The movable switch member 103 is under the control of the relay switch solenoid coil 86 in the same manner that the movable switch member 87 is controlled by said relay switch solenoid coil 86. The movable switch member 103 is biased toward its contact 104 and which is, therefore, its normally closed contact and said switch contact 104 is connected by a wire 106 through circuit functioning indicating mechanism with the other current feed wire 79. The normally open switch contact 105 is connected by a wire 107 with the wire 85 at a point between the limit switch 83 and the relay switch solenoid coil 86 and thereby with current feed wire 79 and, as will presently be obvious, acts as a holding switch for the said coil 86.

35 In other words the closing of limit switch 49 by the accumulation of the desired number of filled containers on accumulator table 47 effects the operation of the pusher and which will push said containers beyond the limit switch thereby allowing it to open but since the movable switch member 103 is now in contact with its normally open contact 105 and the limit switch 97 is closed the current will continue to flow through solenoid switch coil 86 for maintaining its movable members 103 and 87 in contact with their normally open contacts, namely, respectively, 105 and 89.

40 After the pusher 54 has completely transferred the load from the accumulator table 47 to the carriage 84 the limit switch 49 is opened to break its circuit and the limit switch 97 is opened by the abutment 99 and thereby interrupting the circuit through said limit switch 97 and effecting a de-energization of the relay switch solenoid coil 86 and permitting the movable switch members 87 and 103 to return to their normal positions for thereby de-energizing the hydraulic valve shifting electro-magnetic solenoid 77. At the same time the movable switch member 87 in returning to its normally closed position with switch contact 88 completes an electric circuit from the control current source wire 78 by way of wire 90, movable switch member 87, contact 88 and wire 91 to current source wire 79 for thereby energizing the hydraulic valve electro-magnetic solenoid coil 75 and shifting the valve 64 to the position illustrated in FIG. 8 for again connecting the hydraulic medium with conduit 61 for returning the piston 58 and the pusher 54 to their normal positions 65 as illustrated in FIG. 3.

45 The limit switch 97 has mechanically connected therewith a second normally open limit switch 108 which operates a counting mechanism that counts the number of containers, that is, groups of containers, shifted from the 50 accumulator plate onto the carriage, in the casing of half pints, one-third quarts, pints and quart containers, they being four in number, and which counting mechanism at the proper time effects the further operation of the machine. The said counting mechanism is designated in 55 the trade as a rotary switch and as used herein may be

such a commercial switch as manufactured by Automatic Electric Company and exemplified in their "Type 44 rotary switch." Such a switch is diagrammatically illustrated in FIG. 7 and having the elements and parts thereof diagrammatically illustrated and which counter has its said diagrammatically illustrated parts enclosed in a broken line box identified by the reference numeral 109. It should be noted that the limit switch 103 is not physically a part of the said rotary switch but is located at a point remote therefrom and, as noted above, is in fact mechanically connected with limit switch 97 to be operated thereby or simultaneously in connection therewith.

Similarly a manually operable switch, to be subsequently identified and referred to, is not in physical contact with the rotary switch but is in a convenient position with respect to the operator for operating the rotary switch.

The said rotary switch 109 is primarily concerned with and operated by direct current while the rest of the control circuit is operated by and includes alternating current. Accordingly, there is provided a current rectifier 110 having one side thereof connected by a wire 111 with the control circuit feed wire 78 while the other side of said current rectifier 110 is connected by a wire 112 with the second control circuit feed wire 79. The rectifier 110 has one of its output terminals, preferably the positive terminal, connected by a wire 113 with one side of the said limit switch 108; this switch is preferably and hereinafter will be termed the counter switch. The counter switch 108 has its other side connected by a wire 114 with, for convenience, the other output or negative terminal of the rectifier 110 which in turn has connected therewith one end of a wire 115 that terminates at one end of an electro-magnet coil 116 of an electro-magnet 117. The said electro-magnetic coil 116 has its other side connected by a wire 118 with the wire 112 which extends from the rectifier 110.

From the foregoing it will be noted that the closing of the counter switch 108 completed an electrical circuit from the positive pole or outlet of the rectifier 110 through wire 113, said counter switch 108, wires 114 and 115, electromagnet coil 116 and wires 118 and 112 back to the negative pole or outlet of the rectifier 110. The completion of this circuit sets up the operation of the counter.

The counter 109 includes a central operating shaft 119 on which is mounted, in the example of the rotary switch (counter) herein shown, three movable contacts 120, 121 and 122. Associated with each movable contact are a plurality of fixed contacts each illustrated in the drawings as arranged in a fragment of a circle and respectively identified by the reference numerals 123, 124 and 125. The said groups of fixed contacts are known as banks and in connection with the present application the bank 123 is utilized for manually re-setting the counter, as will subsequently be made clear, while the bank 124 is employed as a "homing" bank, in reality, an automatic re-setting of the rotary switch, and the bank 125 as the control switch for the operation of the machine upon accumulation of the desired number of containers on the carriage 84.

Associated with the electro-magnet 117 is an armature 126 pivotally mounted at 127 to a fixed support. The armature 126 has associated therewith a ratchet locking and positioning member 128 which conveniently takes the form of a plurality of ratchet teeth to cooperate with the teeth of a ratchet wheel 129 secured to one end of the rotary switch shaft 119. The armature 126 is normally urged toward the ratchet wheel 129 by a spring 130 and which spring, in reality, is the counter or rotary switch operating motor. Secured to the armature 126, so as to partake of its movements on the pivot 127, is a ratchet pawl 131 with said pawl having a pivot connection at 132 with the armature 126 whereby it is oscillated or actuated into operative engagement with the ratchet wheel 129. In order to insure the operative engagement

of the pawl 131 and ratchet wheel 129 the said pawl is spring biased at 133 toward the ratchet wheel. A yieldable detent 134 is provided to cooperate with the ratchet wheel 129 to hold same and the shaft 119 against movement except as effected by the pawl 131.

Continuing with the electrical connections of the several parts of the rotary switch it should be noted that the rectifier output "plus terminal" has connected therewith one end of a wire 135 that has its other end connected with movable contact 121 associated with fixed bank contacts 124. It should be noted that said bank contacts 124 are eleven in number, actually each of the other bank contacts 123 and 125 are similarly eleven in number. Referring to the bank contacts 124 it will be noted that contacts numbered 4 and 5 are electrically bridged at 136 and have respectively extending therefrom wires 137 and 138 with wire 137 terminating in a wire 139 extending from the wire 115, and with said wire 137 including a manually operable selector switch 140 which is, as shown in the drawings, closed since, in so far as the present description is concerned, it is considered that the machine is casing quart size containers; it should be noted, and as will later be made clear the said selector switch 140 is open when, for example, pint size containers are being cased. The wire 138 from the rotary switch bank contact 5 terminates in a fixed contact 141 of a selector switch which is operable when plural layers of filled containers are placed in a case, as will be subsequently made clear. Contacts 6 and 7 of the contact bank 124 have respectively extending therefrom wires 142 and 143 which terminate in the last mentioned selector switch with the wire 142 connected with a movable switch member 144 while the wire 143 terminates in a second fixed contact 145. The said contact 7 of the bank of contacts 124 is further bridged with each of the bank contacts respectively numbered 8, 9 and 10 by the electrical bridge or wire 146 and which in turn is connected by a wire 147 with the wire 139.

The movable contact 122 associated with the fixed contacts bank 125 has connected therewith one end of a wire 148 which has its other end connected with the wire 111 from the control circuit feed wire 78 and therefore carries alternating current. The said bank of fixed contacts 125 has its contacts numbered 1 and 2 as unconnected with any part of the control mechanism while its contact number 3 has connected therewith one end of a wire 149 that terminates at one side of normally open contacts 150 which are associated with and operated by the electro-magnet 117 upon the energization thereof and the operation of the armature 126 as will subsequently be made clear. The other side of the said normally open contacts 150 are connected by a wire 151 with one end of the solenoid coil 152 of a solenoid switch and which solenoid switch coil 152 has its other side connected by a wire 153 terminating in the control circuit feed wire 79.

The bank contacts 125 has extending from its contacts numbered 5 and 6, respectively, wires 154 and 155 which terminate, respectively, in fixed contacts 156 and 157 that cooperate with a movable contact 158, selectively manually positionable, and from which movable contact 158 extends a wire 159 terminating in the wire 149 at a point between the bank contacts 125 and normally open switch contacts 150, and with said wire 159 having therein a manually operable selector switch 160 adapted to be closed when casing pint containers and since, as noted above, the circuit is being described as casing quart containers the said switch 160 is illustrated in its open position.

Continuing now with the operation of the machine and since a first row or load of containers was shifted from the accumulator table 47 to the carriage 84 and the limit switch 97 and counter switch 108 were operated, the said limit switch 97 causing the energization of the solenoid coil 75 and thereby the immediate return of the pusher 76 leaving a first row of containers on said carriage 84. At

the same time the closing of the counter switch 108 completed the electric circuit above traced for energizing electromagnet 117 and actuating the armature 126 for unlocking the ratchet wheel 127 and positioning the pawl 131. Since the pusher immediately returned the counter switch 108 opened thereby de-energizing the electromagnet 117.

The de-energization of the electro-magnet 117 permitted the driving spring 130, tensioned by the actuation of the armature 126 by the electro-magnet 117, to operate the said pawl 131 in a forward direction and thereby advance the shaft 119 and the movable contacts 120, 121 and 122 from the initial or home position thereof to the contacts numbered 1 in each of the contact banks 123, 124 and 125. Since, at this time and as will later be made clear there is no current to movable contact 120 nothing occurs through this bank. The movable contact 121, being connected through a wire 135 with the rectifier output (plus) terminal effects no operation because its said number 1 terminal is unconnected with any part of the machine. The same thing holds true with respect to the movable contact 122 of bank contacts 125 since the said bank contact 1 is unconnected with any part of control mechanism even though the movable contact is connected through the wires 148 and 111 with the control circuit feed wire 78.

It should be noted that during movement of the pusher 54 for shifting the filled containers from the accumulator table 47, the fence 55 of the pusher 54 prevented further discharge of filled containers from the conveyer 33 effecting, in effect, a stacking up of the containers while the conveyor moved therebeneath. The withdrawal of the pusher 54 to its retracted normal position carried with it, of course, the fence 55 so that the said filled containers on the conveyor 33 immediately commence accumulating on the accumulator table 47 by being pushed by the containers of the conveyer 33 until the load switch 49 is again closed whereupon the cycle above described is repeated.

In the specific example illustrated in the drawings there is required the accumulation of four loads of filled containers, each load of four filled containers, which means that at the completion of the fourth load transfer there are sixteen filled containers on the carriage 84 and which is the exact number of containers required to cover the bottom of the box or case into which the said filled containers are being disposed.

The carriage 84 comprises a carriage table or platform 161 having as a part thereof a side plate 162 and a back plate 163 which together position the load on said carriage. The carriage table or platform 161 is provided on its under surface, since said platform or table is of relatively thin material, with transverse reinforcing members 164 and longitudinally extending reinforcing members 165. The reinforcing members 165 are disposed in vertical alignment with similarly extending members or rails 166 carried by a longitudinally movable frame 167. The frame 167, is formed of angle irons in end abutment with one another and includes longitudinally extending angle irons 168 and 169 which constitute or form, in effect, the support for the carriage as a whole in its movement.

As seen in FIG. 5 the longitudinally extending angle iron 168 has connected with its one leg a roller 170 disposed in a trackway 171 formed between longitudinally extending bars 172 and 173 which are secured to and projecting from a transverse frame or supporting member, specifically identified by the reference numeral 174 in said FIG. 5.

Carried by a second transverse frame member, specifically identified in FIGS. 4 and 5 by the reference numeral 175, are upstanding end supports or blocks 176 and 177 in which is secured a longitudinally extending guide bar 178. The guide bar 178 has mounted on it a bearing block 179 which is in turn secured to the up-

standing leg of the angle iron 169 of the carriage frame 167.

The carriage frame 167 through a plurality of links 180, which are arranged in pairs inwardly of the opposite ends thereof, has floatingly connected therewith the said carriage table or platform 161, see FIGS. 4 and 5. Said links, in pairs, are, respectively, pivoted at one end by pivot 181 with the carriage table or platform depending members 165 and said links are at their other ends pivotally connected at 182 with the frame longitudinal members 166. The arrangement is such that in normal position the carriage table or platform 161 has its longitudinal reinforcing members 165 each disposed on a frame longitudinal member 166 immediately there below, as clearly illustrated in FIG. 5. The parts are yieldably retained in this position by means of one or more springs 183 each spring having one end abutting with an end of the carriage depending member 166 and the other end abutting with the upstanding leg of the front element of the carriage frame 167 and which element is identified in FIG. 4 by the reference numeral 184. Any suitable or desirable means may be employed, such as the inwardly projecting boss 185, for retaining the spring 183 in its operative position.

The carriage including the bottom frame 167 and the table or platform 161 is adapted to be shifted upwardly, as seen in FIG. 3, or to the left, as seen in FIG. 4, for positioning the load filled containers thereon with respect to the elevating mechanism preparatory to being lowered into a case. In order to effect the carriage movement a connecting bracket 186 is conveniently secured to the upper surface of the guide or bearing block 179 to have connected therewith, through a pivotal connection 187, one end of a piston rod 188 which extends from a piston 189 disposed in a cylinder 190 conveniently mounted on a portion of the main frame, such for example, the transverse frame member 175. The cylinder 190 has connected with its opposite ends suitable conduits 191 and 192 through which a hydraulic medium is supplied to the cylinder for reversely actuating the piston 189 and correspondingly actuating the carriage 84.

Continuing with the operation of the machine a second and a third transfer of four filled containers each from the accumulating table to the carriage occurs without changing any of the control circuits as above traced except that the movable contacts 120, 121 and 122 are each advanced through their contacts marked 2 and are now on contacts marked 3. The fourth transfer, however, of the filled containers upon the closing of the counter switch 108 sets in operation the mechanism for actuating the carriage to the position for having its load of filled containers engaged by an elevating mechanism and lowered into the waiting case or basket.

As was noted above the third contact of the contact bank 125 is connected through a wire 149, normally open contacts 150 and the solenoid switch coil 152 with the control circuit feed wire 79. Therefore, the closing of the counter switch 108 at this time in completing a circuit energizing the electro-magnet 117 effects the closing of the said normally open contacts 150. At this time and with the movable contact 122 on contact 3 of the bank contacts 125 an electrical circuit is completed from control circuit feed wire 78 through wires 111 and 148, movable contact 122, contact number 3 of bank contacts 125, wire 149, normally open, now closed, contacts 150, wire 151, solenoid control switch coil 152 and wire 153 back to the other control circuit feed wire 79. The said solenoid coil 152 has its other side connected by a wire 193 with the control circuit feed wire 78 and with said wire 193 including normally closed, now closed, switch contacts 194 and normally open, now closed, switch contacts 195. The switch contacts 195 are under the control of the solenoid switch coil 152 and were, therefore, closed upon the energization of said coil 152 and said normally open, now closed, contacts 195 act as a holding circuit for the solenoid coil 152.

11

This fourth transfer of filled containers from the accumulating table to the carriage, similar to each of the preceding transfers, upon closing the counter switch 108 opened the pusher reversing switch 97 for thereby reversing the pusher to its initial position to permit accumulation of filled containers on the accumulator table or platform.

The above noted normally closed contacts 81 in the circuit including the limit switch 49, operated by an accumulated load of filled containers on the accumulator plate, is under control of the solenoid coil 152 and since said solenoid coil is now being energized the said normally closed contacts 81 are now open for thereby preventing the operation of the pusher even though the limit switch 49 is closed.

The solenoid switch coil 152, also, has under its control a pair of normally open switch contacts 196 having one side thereof connected by a wire 197 with the control circuit feed wire 78. From the foregoing it will be noted that the closing of the counting switch 108 for the fourth time energizes relay switch solenoid coil 152 for closing contacts 195 and maintaining the circuit for the said relay switch solenoid coil 152 and at the same time breaking the circuit which includes relay switch solenoid coil 86 for thereby preventing the operation of the pusher mechanism which includes the limit switch 49 should the accumulator table receive a load of filled containers prior to the complete retraction of the carriage and its positioning in readiness for said subsequent load.

The energization of the relay switch solenoid coil 152 also closes normally open relay switch contacts 196 which are electrically connected by a wire 197 with the control current source wire 78 and are further connected through a wire 198 with the second control current source wire 79. In the wire 198 is an air pressure switch 199 which is normally closed, and so illustrated in FIG. 7, and which switch will be presently further identified. Also in the wire 198 is a limit switch 200 normally open and, again, so shown in the drawings.

The limit switch 200 is a part of the elevator mechanism which lowers the filled containers into the basket or case for subsequent delivery to dispensers of the filled containers. As illustrated in FIG. 1, the limit switch 200 is mounted on or carried by a portion of the elevator mechanism, specifically by the cylinder thereof, as will later be made clear. The said switch 200 includes a movable actuator 201 adapted to be engaged by an abutment 202 upon the upward movement of the elevator mechanism and said switch 200 is, in view of the illustration in FIG. 1, now closed and for the present description of the control mechanism the said switch 200 in FIG. 7 is closed and wherefore an electric circuit from the current supply wire 78 is now flowing through wire 197, normally open now closed limit switch 200 and with current likewise flowing through solenoid 203 of a hydraulic control valve mechanism now to be described.

As was noted above the cylinder 190 has connected with its opposite ends conduits 191 and 192 and which conduits terminate in a control valve mechanism 204, shown in elevation in FIG. 3 and in diagrammatic detail in FIG. 8. As shown in said FIG. 8 the said conduits 191 and 192 terminate in suitable ports in a valve sleeve 205 which has disposed therein a spool type valve 206 which, similar to the valve member 64, is provided with a plurality of lands identified by the same reference numerals as above, forming between them circumferential connecting grooves for alternately connecting the said pipes or conduits 191 and 192 with the pressure pipe or conduit 68 from the hydraulic medium pump 69 and with the discharge pipe or conduit 73 and the tank or sump 71. As illustrated in the drawings, particularly FIG. 8, the pressure pipe or conduit 68, particularly by the position of its valve 206, is connected with the pipe or conduit 191 for thereby holding the piston 189 in the position illustrated therefor in FIG. 3 and holding the carriage mecha-

12

nism 84 in its retracted position and at this time the pipe or conduit 192 is connected with the hydraulic medium sump or tank by way of the discharge pipe or conduit 73. The completion of the electric circuit by the fourth closing of the counter switch 108 energized the solenoid 203 and which solenoid 203 similar to the solenoid 77, above, is associated with the valve 206 for shifting same to its second position, namely, to the left hand end of the valve sleeve 205 as illustrated in FIG. 8 for thereby connecting the hydraulic pressure pipe or conduit 68 with the pipe or conduit 192 and the lower end of the cylinder 190 as seen in FIG. 3. The connection causes piston 189 to move upwardly in the cylinder 190 to carry with it the piston rod 188 and carriage mechanism 84 with its load of filled containers.

The carriage mechanism 84 moves until it is arrested and stopped. The carriage table or platform 161, see FIG. 4, has at its inner end one or more rollers 207, preferably two, see FIG. 3 freely rotatable on the axle bolt carried by a bracket 208 depending from the under surface of the said carriage platform 161. In the path of the said roller 207 the frame of the machine is provided with an abutment 209 that engages with the rollers 207 for thereby arresting the movement of the said carriage table or platform 161. The stopping of the movement of the carriage table or platform 161 does not stop the movement of the carriage supporting frame 167 but actually permits the continued movement of said carriage frame. The continued movement of the carriage frame 167 with the stopping of the table or platform 161 causes said table or platform to be elevated through the links 180 since, as is obvious from FIG. 4, the movement of the carriage frame will tend to move the pivots 182 forwardly and cause the links to move therewith and oscillate them about said pivots to a position to dispose the said links other pivot 181 in a position vertically of the said pivots 182. The purpose of this construction, as will later be made clear, is to permit the freeing of the loaded containers from the carriage prior to the withdrawal of the carriage from beneath the said filled containers.

The carriage mechanism frame 167 has, see FIG. 3, upstanding therefrom an abutment 210 which when the carriage mechanism 84 reaches its innermost position and with its table or platform 161 elevated, engages the movable element or switch actuator 211 of a limit switch 212 carried by the frame of the machine in the vicinity of the stop 209.

As illustrated in FIG. 7 the limit switch 212 is a normally open switch and has one side thereof connected by a wire 213 with the control current supply wire 78. The other side of the said limit switch 212 is connected by a wire 214 with the other control current supply wire 79 and with said wire 214 including the solenoid coil 215 of a relay switch. The relay switch of solenoid coil 215 includes the normally closed switch contacts 194 in wire 193 and which normally closed switch contacts 194 are now opened for breaking the above described holding circuit that includes relay switch solenoid coil 152 for thereby de-energizing said relay switch solenoid 152 and opening, normally open, relay switch contacts 196 for breaking the above described electrical circuit including the valve electro-magnetic solenoid 203.

The energization of the relay switch solenoid coil 215 also closed normally open switch contacts 216 which have one side thereof connected by a wire 217 with the control current supply wire 78 and which normally open, now closed, relay switch contacts 216 have their other side connected in part by a wire 218, a strap 219 and a wire 220 with the other control current supply wire 79 and with said wire 220 including therein the solenoid coil 221, of a relay switch. The relay switch of the solenoid coil 221 has associated therewith normally open, now closed, relay switch contacts 222 and which have one side thereof connected with the control current supply

wire 78 through a wire 223 which includes normally closed, now closed, limit switches 224 and 225. The normally open now closed relay switch contacts 222 have their other side connected through a wire 226 with the other control current supply wire 79 and which wire 226 includes an electro-magnetic solenoid 227 of a compressed air control valve 228 diagrammatically illustrated in the pneumatic circuit in FIG. 9. It should be noted that the strap wire 219 extends between or connects the wires 218 and 226.

As will be noted in FIG. 3 each of the filled containers has its closing flap, known in the trade as a "gable," and indicated in FIGS. 11 and 12 by the numeral 26, extending in the same direction and which is the direction of movement of the carriage mechanism 84 as above described. The said movement of the carriage mechanism carries the filled containers to a position to be gripped or grasped by a gripper mechanism forming a part of the elevator mechanism. As shown in FIGS. 1 and 3 the gripper mechanism comprises a fixed jaw 229 for each filled container and located on one side of each container gable. The said fixed jaws 229 are carried by a suitable framework including depending end members such as shown at 230 in FIG. 1 and in which is oscillatably or rotatably mounted rods or bars 231, there being as many such rods or bars as there are rows of filled containers. Secured to and movable with said bars or rods 231 is a movable jaw 232, there being as many movable jaws as there are fixed jaws 229. Connected with each rod or bar 231 at each end thereof and to upstand therefrom is a lever 233 with said levers at the similar ends of the rods or bars 231 having their upper ends pivotally connected through a strap 234. To insure the proper operation of the movable jaws there is, preferably, a lever 233 at each end of each bar or rod 231 which have their upper ends connected by a similar strap 234; said lever and strap mechanism for one end of the rods or bars 231 being illustrated in FIG. 1, in elevation, and the said lever and strap arrangement for the other ends of said rods or bars 231 being illustrated in FIG. 3, in plan. The said levers and straps are connected for uniform and simultaneous operation by means of a tie bar 235, shown fragmentarily in FIG. 3 and extending from the strap at the back end of the gripper mechanism. The said tie bar 235 is connected, substantially midway of its length, to the outer end of a piston rod 236 projecting from a cylinder 237 which is carried by a horizontal plate 238 forming a part of the frame of the gripper mechanism. The said gripper mechanism is a part of the filled container elevator mechanism, as noted above, and as will presently be made clear.

The gripper cylinder 237 is diagrammatically illustrated in FIG. 9 and is shown as having extending from opposite ends thereof conduits 238 and 239. FIG. 9 further diagrammatically illustrates the piston rod 236 as having at its inner end a piston 240 with the conduits 238 and 239 on opposite sides of said piston 240. The pipes or conduits 238 and 239 have their other ends connected with the air valve 228 and as illustrated has the pressure pipe or conduit 238 connected for actuating the piston 240 to an open position for the gripper mechanism. The energization of the solenoid 227 effects the shifting of the valve 228 for connecting the pipe or conduit 239 with the air pressure line 241 and simultaneously connecting the conduit 238 with the exhaust pressure line 242 or atmosphere. This then permits the piston 240 to be actuated and through the piston rod 236 operate the gripper movable jaws 232 for now gripping the gables of the filled containers located within the gripper device.

Disposed in the pressure line 239 is a pressure switch mechanism 243 illustrated in FIG. 9 as including the above identified normally closed switch 199 and additionally including a normally open switch 244. As diagrammatically illustrated in said FIG. 9 the pressure switch 243 includes a diaphragm 245 which effects the

opening and closing of the switches 199 and 244 and which diaphragm is operated by the pressure in the pressure line 239 and for which purpose the said pressure switch mechanism 243 is connected by a pipe or conduit 246 with the said pressure line 239.

As illustrated in FIG. 7 the normally open pressure switch 244 has connected at one side thereof wire 247 terminating in wire 198 and control circuit feed wire 78 and which wire 247 includes an electro-magnetic solenoid 248. The other side of the normally open pressure switch 244 is connected by a wire 249 with the current source supply wire 78.

From the foregoing it should be noted that after sufficient pressure has been built up in the gripper cylinder 243 to securely grip each of the filled containers said pressure closes the switch 244 and opens the normally closed switch 199 for thereby rendering the circuit including the same inoperative so that the subsequent closing of the normally open switch contacts 196 will not complete the circuit.

The electro-magnetic solenoid 248 is connected with the valve stem 74 of the valve 206 for returning said valve 206 to the position thereof illustrated in FIG. 8 for reTRACTING the carriage mechanism 84 to its position for receiving a subsequent load of filled containers from the accumulator table 47. Upon full retraction of the carriage mechanism 84 the normally open limit switch 83 is closed for thereby readying the circuit including the same and which circuit is subsequently closed by the closing of the limit switch 49 upon the completion of an accumulated load on the accumulator table 47 as above pointed out and whereupon the cycle including the pusher 54 is started.

The limit switch 83 is in reality a double switch including normally open limit switch 250 which is in the electric conduit or wire 218 extending from the normally open relay switch contacts 216 and with said wire 218 further including electro-magnetic solenoid coil 251 connected by wire 252 with the current supply wire 79. Also included in the wire 218 is the normally open relay switch contacts 253 and the normally closed relay switch contacts 254.

The normally open relay switch contacts 253 are under the control of the relay switch solenoid coil 255 which is included in an electric conductor or wire 256 extending between the control current wires 78 and 79. Included also in the electric conduit or wire 256 is normally open limit switch 257 which is a part of the positioning mechanism for the case into which the filled containers are now to be disposed.

The limit switch 257 is located on the frame of the machine or at least on the supplemental frame which carries a conveyer mechanism indicated in general by the reference numeral 258 on which the container cases are mounted to have loaded therein the filled containers. The said limit switch 257 is closed by a case, indicated by the reference numeral 259, see FIG. 1, and therefore may be considered as closing the said circuit and including the relay switch solenoid coil 255.

Since the limit switch 257, for the present is to be considered as closed by the case 259 and will remain closed so long as said case is positioned as in FIG. 1, the relay switch solenoid coil 255 is energized for closing the normally open relay switch contacts 253 and thereby effecting a circuit from the electric current source wire 78 by way of wire 217, normally closed now closed relay switch contacts 254, normally open now closed relay switch contacts 253, normally open now closed relay

switch 250 for energizing electro-magnetic solenoid 251 which has its other side connected by a portion of the wire 252 with the electric current supply wire 79.

The electro-magnetic solenoid 251 is associated with the valve stem 76 of a valve 260 which is a part of a valve mechanism similar to valve mechanisms 62 and 204. The valve 260, is therefore provided with lands

to form therebetween connecting grooves for connecting the hydraulic pressure line 68 alternately with hydraulic conduits or pipes 261 or 262 and connecting the other of said pipes or conduits with the hydraulic return line 73 and the tank or sump 71. The valve 260 controls the operation of a piston 263 disposed in a cylinder 264 and extending vertically of the central part of the machine frame. The piston rod 265 has secured to its lower end a plate 266 which forms a part of the frame which carries the filled containers gripper mechanism.

The cylinder 264 has connected with its upper end the other end of the pipe or conduit 261 while the lower end of said cylinder has connected therewith the other end of the pipe or conduit 262.

From the foregoing it will be noted that upon the gripping of the filled containers by the gripper jaws and upon the building up of sufficient pressure to indicate said containers are properly gripped the carriage mechanism 84 is retracted to its position for receiving a new load. Upon the full retraction of the carriage mechanism 84 and the proper clamping of a case beneath the gripper mechanism the limit switch 83 is closed and the limit switch 257 is closed for thereby permitting the lowering of the gripper mechanism to the bottom of its stroke to deposit the filled containers on the case bottom.

During the operation of the carriage mechanism 84 from its retracted position to its position beneath the gripper means and return to its normal load receiving position, the rotary step switch or counter mechanism 109 was re-setting itself preparatory for the next cycle. Upon the closing of the counter switch 108 for the fourth time and the completion of the electrical circuit which opened the normally closed switch 81 the electro-magnet 117 actuated or loaded the armature 126, in the same manner that had been effected on each of the three preceding transfers, and upon the retraction of the pusher from its said fourth advance the counter switch 108 again opened to de-energize the electro-magnet 117 and permit the spring or drive operation of the armature 126 and advancement of the movable contacts 120, 121 and 122 to the contact 4 of their respective bank contacts.

The advancement of the movable contact 121 to its bank contact 4 set up an electric circuit from the rectifier output positive terminal through wire 135, movable contact 121, contact 4 of bank contacts 124, wire 137, including closed selector switch 140, wire 139, normally closed, now closed, switch contacts 267 in said wire 139 and which wire 139 terminates in the wire 115 to the electro-magnet coil 116 and which normally closed contacts 267 are opened upon energization of said electro-magnet 117. The electric circuit being described continues from the other end of the electro-magnet coil 116 through wires 118 and 112 to the other, negative, terminal of the current rectifier 110. This circuit obviously energizes the electro-magnet 117 for actuating the armature 126 and loading its spring 136. As soon as the electro-magnet 117 is energized the normally closed contacts 267 are opened for de-energizing the electro-magnet 117 and thereby permitting the advance of the movable contacts 120, 121 and 122 to contact 5 of their respective bank contacts.

The advancement of the movable contact 121 to contact 5 of its bank contacts 124 completes the same circuit as above described, but including the bridge or wire 136 between contacts 5 and 4 of bank contacts 124. This causes the advancement of the movable contacts 120, 121 and 122 to contact 6 of their respective bank contacts.

The advancement of the movable contact 121 to contact 6 of bank contacts 124 effects the completion of an electrical circuit in the main as above pointed out for bank contacts 4 and 5. Specifically this circuit includes the wire 135 from the plus outlet terminal of rectifier 110, movable contact 121, contact 6 of contact bank 124, wire 142, movable and fixed contacts 144 and 145 of switch indicated in its entirety by the reference numeral 141a, 75

wire 143, bridging or wire 146 of contacts 7, 8, 9 and 10 of bank contacts 124, wires 147 and 139, normally closed now closed contacts 267, wire 115, electro-magnet coil 116 and wires 118 and 112 back to the other or negative output terminal of the rectifier 110. This electrical circuit again energizes the electro-magnet 117 and substantially, immediately breaks the circuit and causes the advancement of said movable contacts 120, 121 and 122 to contact 7 of their respective bank contacts.

10 The advancement of the movable contact 121 to contact 7 of its bank contacts 124 again completes an electrical circuit as above described in connection with bank contact 6 except that the switch 141a is now bypassed, the circuit being complete through the bridging 146 to wire 147 and on through the magnetic coil of the electro-magnet 117. The completion of the electric circuit again advances the movable contacts 120, 121 and 122 to their bank contacts 8, 9 and 10 each time completing an electric circuit to effect the self advance or "homing" of the movable contacts.

15 Upon the advancement of the said movable contacts from their respective bank contacts 10 to their respective bank contacts 11 the circuit is broken since the "homing" bank contacts 124 does not have its contact 11 electrically connected with any circuit.

20 It should be here noted that the positioning of each of the movable contacts 120, 121 and 122 on contact 11 of their respective bank contacts 123, 124 and 125 is the equivalent of the positioning of said movable contacts 30 as illustrated in FIG. 7. This is accomplished, in the physical embodiment of the counter mechanism or rotary stepping switch 109, by supplying the shaft 119 with three equally spaced movable contacts for each bank of fixed contacts and which movable contacts in succession 35 effect the cycle of operation as above described.

25 In order to complete the description of said counter mechanism or rotary stepping switch 109 and establish the purpose of the above noted "re-setting" bank of contacts 123 it will be noted that the movable contact 120 has connected therewith one end of a wire 268 which has its other end connected with a manually operable switch 269 and which switch 269 has its other side connected by a wire 270 with the wire 113 and therefore the outlet positive terminal of the rectifier 110. It will further 40 be noted that the said re-setting bank contacts 1 through 6 are each electrically connected with one another through a wire or bridge 271 and with said contact 6 having connected thereto the end of the wire 139.

30 The switch 269 is a manually starting switch and is 45 employed to insure the counter mechanism being in its initial or home position before the initial starting of a machine cycle. Assuming that the machine had previously been stopped with the movable contacts 120, 121 and 122 on a fixed contact other than its initial or 50 home contact, the closing of the manual starting switch will complete an electric circuit from the output positive terminal of the current rectifier 110 through wires 113 and 270, starting switch 269, wire 268, movable contact 120, the particular bank contact 1 to 6 of bank contacts 55 123 on which said movable contact last stopped, bridge or wire 271 and wire 139 for completing the electro-magnet circuit and advancing the movable contacts as above 60 pointed out. The holding of the starting switch 269 closed will repeat the advancement of the movable contacts at 65 least through contact 6 whereupon the movable contact 121 of the "homing" bank contacts 124 will take over and complete the homing of the said movable contacts 120, 121 and 122 to the positions thereof illustrated in FIG. 7.

70 From the foregoing it will thus be seen that the counting mechanism or rotary stepping switch 109 is automatically re-set after the operation of the carriage mechanism 84 preparatory to a subsequent operation thereof upon the transfer thereof of a load of filled containers.

Continuing with the assumption that the machine is

operating on or casing quart size containers, as illustrated in the drawings, a manually operated selector switch 272, located at the upper end of the said central part of the machine frame structure, see FIG. 1, is maintained closed during the casing of quart size filled containers and which switch 272, see FIG. 7, has one side thereof connected by a wire 273 with the control current feed wire 78 while its other side is connected by a wire 273a with a wire 274 that extends between the control current feed wires 78 and 79 and with said wire 274 including a relay switch solenoid coil 275, normally open relay switch contacts 276 and normally open, now closed, relay switch contacts 277. The selector switch 272, being closed, during the movement of the elevator mechanism energizes said relay switch solenoid coil 275 for the closing of the relay switch contacts 276 and which contacts 276 act as a holding contact for the said relay switch solenoid coil 275.

It should be noted that the circuit including normally closed limit switch 225 is provided with a bypass circuit which includes a wire 278 having one end connected with the control circuit wire 223 at a point between said normally closed limit switch 225 and normally open relay switch contacts 222. Said bypass circuit wire 278 has therein a manually operable switch 279 which is open, and so illustrated, when filled containers of a quart size are being loaded or cased and which switch is closed when other sizes of filled containers are being loaded or cased, as will presently be made clear. The said bypass circuit wire 278 in addition to the switch 279 includes normally closed relay switch contacts 280 which are associated with and under the control of relay switch solenoid coil 275 and while said normally closed switch contacts 280 are now closed the bypass circuit wire 278 is not complete due to the open switch 279 therein.

The elevator mechanism continues to descend toward the bottom of the case or box and just before the filled cartons reach the bottom of said case or box they are released from the gripper mechanism and the elevator mechanism returned to its upper position, by mechanism now to be described. The gripper and elevator mechanisms include, as noted above, the plate 266 to which the piston 263 is connected with said connection, as illustrated in FIGS. 1 and 4, including a knuckle or pivot joint 281 and with the ends of said plate 266 welded or otherwise secured to a pair of upright members 282 and 283 which constitute the elevator frame and which upright members 282 and 283 have their upper ends connected to opposed sides of a pair of strap plates 284. One of the said plates, preferably the one to the front of the machine, has at its upper end a cam box 285 in which is mounted the means for operating the limit switches 224 and 225 at the proper moment and depending upon which size of filled containers is being boxed or cased.

Any suitable or desirable means may be employed for this purpose, that shown in the drawings comprising a pair of aligned shafts 286 and 287 each journaled in the upper and lower walls of the control mechanism or cam box 285. The shafts 286 and 287 project above the said control box and each, respectively, is provided with a knob 288 and 289 whereby said shafts are rotated and to insure their simultaneous rotation or angular adjustment, since their angular positions with respect to one another is important, the said shafts are interconnected by a pair of intermeshed gears or pinions 290. Mounted on said shafts are fingers or cams with shaft 287 having thereon fingers 291, 292, 293 and 294 while the shaft 286 has thereon the fingers or cams 295, 296 and 297.

The elevator mechanism including the control box 285 is guided in its vertical movement by guide blocks 298 from each end of each of the strap plates 284, or from each corner of the frame, with said guide blocks each having centrally thereof a guide rod 299 which has its upper end suitably secured to an upper transverse frame member 300. The said guide rods 299 have their lower

ends secured in or to a transverse frame member 301 which conveniently includes a part of the motor supporting frame 46, above identified.

For the present description of the machine, it is assumed 5 that the control box 285 has its shafts operated to the positions whereby the finger or cam 291 is forwardly projecting. The said finger or cam 291 in its operative position will engage and open limit switch 225 which, as seen in FIG. 1, is mounted on a transverse frame member 10 302.

The limit switch 225 is provided with an oscillatable or 15 rotatable actuator 303 located in the path of movement of the finger or cam 291 and the parts are so related to one another that the finger 291 actuates the limit switch 225 for opening the same when the filled containers, as noted above, are just above the bottom of the box or case and the said opening of the limit switch causes the release of said filled containers as follows.

The air control valve 228 was shifted, as noted above, 20 by the electro-magnetic solenoid 227 to effect the operation of the said gripper jaws. As seen in FIG. 9 the shifting of said valve 228 to the right for thereby connecting the air pressure line 241 with the cylinder line or conduit 239. This shifting of the said valve 228 was against the 25 resistance of a spring 304 and the opening of the normally closed limit switch 225 de-energized the said electro-magnetic solenoid 227 for thereby relieving the tension in the spring 304, and permitting the said spring to shift the valve 228 to the position illustrated in said 30 FIG. 9 and which may be termed the normal open position of said valve and thereby connecting the air pressure line 241 with the cylinder 237 on the side of the piston for opening the clamp or gripper jaws on the containers.

35 The said operation of the valve 228 thereby released the pressure switch 243 and permitting the closing of the normally closed switch contacts 199 and the opening of the normally open switch contacts 244 for subsequent operation of the electro-magnetic solenoid 203.

40 More importantly, at this time, the opening of the normally closed limit switch 225 broke or disconnected the electric circuit including relay switch solenoid coil 221 for thereby permitting the closing of normally closed relay switch contacts 305 which are in the control circuit 45 or wire 252 a portion of which was above referred to and which wire includes electro-magnetic solenoid 306.

The electro-magnetic solenoid 306 is associated with the valve stem 74 of the valve 260 and returns the said valve 260 to the position illustrated therefor in FIG. 8 50 for thereby connecting the hydraulic pressure line 68 with the pipe or conduit 262 and the lower end of the elevator cylinder 264 for causing the upward movement of the piston 263 therein. This upward movement of the piston 263 continues until the said piston reaches its 55 uppermost position.

It will be noted that the limit switch 225 is in reality a double switch including the normally closed switch contacts 225 and also including normally open limit switch contacts 307 and which switch 307 is included in an electric conduit or wire 308 extending between the control circuit current wires 78 and 79 with said wire 308 including normally open relay switch contacts 309, under the control of relay switch solenoid coil 275 now energized and wherefore said normally open relay switch 60 contacts 309 are closed, and said electrical conduit or wire 308 further includes the relay switch solenoid coil 310 of a relay switch which controls the normally closed relay switch contacts 277 and 254. The closing of the limit switch 307, however, completes the electric circuit 65 for energizing the relay switch solenoid coil 310 and effects the closing of the relay switch holding switch contacts 311 which are normally open. The said normally open, now closed, relay switch contacts 311 are included in the electric conduit or wire 312 which extends from the control circuit current wire 79 to the wire 308 at a 70 75

point between the normally open relay switch contacts 309 and relay switch solenoid coil 310. Included in the electric conduit or wire 312 are normally open relay switch contacts 313 which are under the control of relay switch solenoid coil 255 and now energized by the closed, though normally open, limit switch 257 and which limit switch 257 is closed by the case being loaded.

The energization of the relay switch solenoid coil 310 opened normally closed relay switch contacts 314 which are under the control of said relay switch solenoid coil 310. The said normally closed relay switch contacts 314 are included in an electric conductor or wire 315 extending from a point between the limit switch 257 and the relay switch solenoid 255 with said electric conduit or wire 315 including an electro-magnetic solenoid 316.

The electro-magnetic solenoid 316, see FIG. 9, is associated with air valve 317 and which valve 317 insofar as the present description is concerned, and as disclosed in the drawing, is in its left hand position against the resistance of the spring 318. In this position compressed air in conduit or pipe 319 is prevented from flowing through the said valve. At this time a branch air line or conduit 320 extends to an air control valve 321 and with a second air conduit 322 carrying air to a valve mechanism 323. Extending from the valve mechanism 317 is a restricted air line 324 that terminates in a valve shifting mechanism 325 for the valve mechanism 323 and which valve mechanism 323 is a normally closed valve wherefore actuated to the position shown in FIG. 9 by the spring 326. Extending from the valve mechanism 323 is an air conduit 327 which passes through an air flow regulator 328 to one end of a cylinder 329 in which is disposed a piston 330 that has projecting from it a piston rod 331 connected with mechanism for clamping the box or case 259 in the position illustrated in FIG. 1 and which, as noted above, is the loading position for the case. The actuation of the piston 330, as will presently be made clear, is against the resistance of a spring 332.

From the foregoing it should be noted that upon the closing of limit switch 257 by the case and the completion of the circuit including the electro-magnetic solenoid 316 the valve mechanism 317 was actuated to permit a flow therethrough which was through the conduit or line 324 for energizing the air valve shifter 325 and shifting said valve 323 from its normally closed position to an open position for thereby connecting the air pressure line 319 through conduits or air pressure lines 320 and 322 with the conduit 327 and actuating the case clamping piston 330.

The energization of the relay switch solenoid coil 310 by the closing of the normally open limit switch contacts 307 opens the relay switch normally closed contacts 314 thereby de-energizing the solenoid 316 and permits the spring 318 to return the valve 317 to the position illustrated in FIG. 9 and connect the line 327 to the atmosphere thereby rendering the valve shifter 325 inoperative and the return of the valve 323 to its normal position by the spring 326 and thereby connect the case clamping cylinder 329 to atmosphere and permit the spring 332 to release the clamp piston so that the case with its load may be released. It should be noted that there is a time delay mechanism 333 in the air line to delay withdrawal of the piston 330 to insure clearance of the filled case by the elevator.

The energization of the solenoid 316 by the positioning of the case, as noted above, shifted the valve 317 from its normally closed position to its open position thereby permitted the flow of compressed air into the line 324 to open the normally closed valve 323 and permit flow therethrough from the conduit 322 to the conduit 327. This flow of air in conduit or line 327 also caused a flow of air in the conduit or line 334 to a valve actuator 335 associated with the normally open valve 321 and which is illustrated in its normally open position under the influence spring 336. Therefore, the shifting of the valve

323 to its normally closed position and connecting the pipe or line 327 to exhaust also connects the line or pipe 334 to the exhaust and effects the de-energization of the valve actuator 335 and the shifting of the said valve 321 to its normally open position and permit flow therethrough from the conduit 320. This flow of air from the said valve 321 to a valve 337, by way of pipe or conduit 338, also effects an air flow through a pipe or conduit 339 to a valve actuator 340 associated with the said valve 337. This flow of air in the conduit 339 is restricted so that a time delay is provided before the said valve actuator is permitted to actuate the said valve 337 against its spring 341 to shift it from its normal position for connecting the air flow in conduit 338 with the conduit 342 including air flow control valve 343 and the cylinder 344. The cylinder 344 includes a piston 345 with a piston rod 346 connected, as will later be made clear, with a case ejector mechanism. The shifting of the piston 345 in a case ejecting direction is against the yielding resistance of a spring 347.

As will be noted from FIG. 1 the case 259 is to the left of its conveyer and held there by a clamp shoe 348 and that the upper left hand corner of the case is against a block or a shoe 349. Upon the case receiving its load the clamp shoe is released, as above pointed out, whereupon the pneumatic mechanism above described comes into operation for shifting the said case 259 away from or laterally of the stop 350, whereupon the case with its load is transported from beneath the elevator mechanism. Due to the time delay and retracting mechanisms built into the ejector system the said ejector shoe is actuated and after shifting the loaded case clear of the stop is retracted so as not to interfere with the empty case being brought into engagement with the said stop 350.

From the foregoing it will be noted that the deenergization of the solenoid 316 not only effects an unclamping of the filled case but at the same time effects the operation of a filled case ejector mechanism for shifting the said full case from the loading position and permitting the placement of an empty case in position to be loaded.

The positioning of the empty case again closes the limit switch 257 to permit the depositing therein of filled containers. The cycle of the mechanism had been progressing as above set forth so that a new load of filled containers are now on the carriage mechanism 84 for transfer to the elevator.

As was noted above the cycle of the machine just described was for handling sealed containers of a quart size and which containers are deposited in a single row, per case, on the bottom thereof. As was noted above when operating on or loading pints into a case it is desired that an upper layer, such as a half layer, or a three-fourths layer, is to be placed upon the full layer on the case bottom. Assuming now that pint size containers are to be cased, and that a half layer of filled containers are to be placed on the full layer in the case, certain adjustment are made in the machine and in the electric control circuit, said adjustment in the electric circuit being the opening of the manually operable switch 140 and the closing of the manually operable switches 160 and 279 and, if not already effected the positioning of the movable contact 144 into engagement with fixed contact 145 of switch 141a and the positioning of movable contact 158 into engagement with fixed contact 156 of switch 156a. The said switch 156a has, for convenience, been so designated in its entirety and includes fixed contacts 156 and 157 and movable contact 158 with said movable contact being mechanically tied or connected with the movable contact of switch 141a for simultaneous movement of the movable contacts 144 and 158.

It will be appreciated that the accumulator table 47 and carriage platform 161 remain in the same plane regardless of the size of the container being loaded in the machine and that, therefore, the distance between the bottoms of said container and the bottom of the

basket or case 259 remains the same and necessitates the same distance of travel of said container bottoms. However, in view of the fact that the said containers are of different heights, that is, decreasing in height from, for example, the quart, to the pint, to the third quart, and to the half pint, the gripper mechanism must be lowered to a position for receiving the smaller height containers. To effect this adjustment the entire elevator mechanism along with the piston and cylinder mechanism are lowered thereby permitting the piston to travel to the same point before releasing its load after the gripping of the smaller height containers. Any suitable or desirable means may be provided to accomplish this result, preferably, at this time, the means illustrated in the drawings being utilized and which means specifically are as follows.

As seen in FIG. 2 the uprights of the machine frame are joined by a horizontal frame member 351 in which is mounted a guide bushing 352 secured in position by a flange 353 and with said flange disposed on the upper surface of the horizontal frame member 351 and with the sleeve thereof depending below said frame member. Disposed in said sleeve is a rod or bar 354 having projecting from one side thereof a key 355 that passes through a suitable keyway 356 formed through the bushing 352. The bar 354 has secured to its lower end a clevis head 357 including a slot 358 in which is disposed a tongue 359 carried by and upwardly projecting from a cylinder head 360 at the upper end of the cylinder 264. The said cylinder head 360 has connected therewith the pipe or conduit 262. The clevis 357 and the cylinder head tongue 359 are connected to one another by a pin 361 which extends therethrough.

The upper end of the rod or bar 354 is provided with screw threads 362 in threaded engagement with a nut 363. The nut 363 is rotatably mounted in a bushing or sleeve 364 and which nut 363 has a flange at its lower end engaging a lower surface of the sleeve 364 and the said nut 363 has at its upper end a screw collar 365 which engages the upper surface of the sleeve 364. The sleeve 364 has a radial flange 366 through which it is secured to a transverse frame member 367 at the upper ends of the central frame uprights. The screw collar 365 includes a sprocket 368 about which is trained a sprocket chain 369. The sprocket chain 369 is in turn trained around a driving sprocket 370 at the upper end of a shaft 371 rotatably journaled in a suitable bearing 372 carried by one of the framing uprights. The shaft 371 above the sprocket 370 is provided with an actuating handle or lever 373.

The upper end of the said rod or bar 354 has secured to it a collar 374 and which collar operates the normally open limit switch 272 for closing same when the machine is adjusted for loading or casing filled quarts and which limit switch is therefore open at the commencement of a cycle which loads or cases filled containers of a size other than said quarts.

From the foregoing it will be noted that actuation of the nut 363 through the handle or lever 373 and sprocket chain 369 in the desired direction will cause the screw 362 to be lowered and with it, since it is integral, the rod or bar 354 and elevator cylinder 264 along with its piston 263 and the parts carried thereby which, of course, includes the gripper mechanism at the lower end of the said piston rod. Since the gripper mechanism includes the transverse plate 266, to which the elevator frame members 282 and 283 are attached and which in turn carry the connecting plates 284 and guide block 298 the entire elevator mechanism is accordingly vertically adjusted. The machine is further adjusted through the knobs 288 and 289, which in the case of loading pint containers, effects the withdrawal of the finger 291 on the shaft 287 and the bringing into play of fingers or cams 292 and 295 respectively on said shafts 287 and 286.

With these adjustments in the machine structure and

the control circuit the machine is started in motion by operating the hydraulic pump motor and the filled container conveyer motor 44.

The machine functions, initially, substantially the same as above described which includes the accumulation of four successive rows of filled containers on the accumulator table 47 each closing the limit switch 49 and counter switch 108 which through the fourth closing thereof caused the cycle above described in lowering of a full layer of filled containers into the case.

The complete shifting of the carriage mechanisms to its operative position with respect to the gripper mechanism effects the operation of said gripper mechanism in the same manner as above set forth but at the same time sets in operation supplemental control mechanism through the counter mechanism 109, as follows:

With the machine set for casing pints, particularly when it is desired to place a half second layer in the case, the closing of the counter switch 108 the fourth time and through the movable contact 122 while energizing the solenoid 152 for preventing the operation of the machine until the carriage mechanism 84 has been returned to its normal position does not effect the discharge of the case from its loading position nor does the counter mechanism 109 return to its normal or home position. This holding of the counter mechanism against "homing" is effected because the manually operable switch 140 being now open the movable switch 121 upon reaching contact 4 of bank contacts 124 does not complete an electric circuit through the wire 137. From this it follows that the shifting of the fifth load of filled containers from the platform has the same effect as the shifting of the first load of the original layer. When, however, the sixth load is shifted and with the movable contact 122 on contact 5 of bank contacts 125 the closing of the counter switch 108 then completes an electric circuit through the energization of the electro-magnet 117 and the closing thereby of normally open switch contacts 150 as follows:

From control circuit feed wire 78 through wires 111 and 148, movable contact 122, contact 5 of bank contacts 125, wire 154, fixed contact 156, movable contact 153, wire 159 including now closed manually operable selector switch 160, normally open now closed contacts 150, wire 151, solenoid switch coil 152 and wire 153 to the control circuit feed wire 79. The energization of said solenoid switch coil 152 closes its own normally open now closed holding contacts 195 as well as closing normally open contacts 196 and opening normally closed contacts 83 and permits the operation of the machine to the extent of discharging the now filled case and positioning an empty case for subsequent loading.

At this time also the advancement of the movable contact 121 to contact 6 of bank contacts 124 upon the opening of the limit switch 108 effects the "homing" of the counter switch through the said circuits as above described upon the said movable contact 121 reaching contact 6 of bank contacts 124 when the said selector switch 140 was closed.

As was noted above it is sometimes desirable, purely a users choice, to place a three-quarter second layer in the case and in order to accomplish this the movable contact 144 of manually operable switch 141a is shifted from the fixed contact 145 to the fixed contact 141 and simultaneously the movable contact 158 of the switch 156a is shifted from its fixed contact 156 to the fixed contact 157. With said switches 141a and 156a so adjusted it is believed obvious that the discharging of the loaded case is prohibited until after the transfer of the seventh load from the accumulator table since it is only after the said seventh transfer and with the movable contact 122 on contact 6 of bank contacts 125 that the control mechanism is set up for the shifting of the filled case. Also it is believed obvious that with the switches 141a and 156a in their above identified adjusted posi-

tions that the "homing" of the rotary switch can only take place upon movable contact 121 reaching contact 7 of the bank contact 124.

It is believed also obvious that whether a layer and a half or a layer and three-quarters are placed in the case the machine will re-set itself for a second complete cycle.

As soon as the grippers have picked up the incomplete or partial layer of filled containers, as pointed out above, the carriage is retracted to its loading position whereupon the elevator descends to the case.

At this time, and as pointed out above, there is a layer of filled containers upstanding from the case bottom and the present partial load of filled containers is to be deposited onto said full layer but the elevator is not to descend to its lowermost position and is therefore arrested in its descent above said lowermost layer of filled containers, this is effected by the opening of the limit switch 225 which de-energizes the circuit including the electro-magnetic solenoid 227 to permit the retraction of the gripper jaws to release the said filled containers and at the same time de-energizes the relay switch solenoid coil 221 for breaking the circuit thereto and at the same time permits the closure of normally closed relay switch contacts 305 which are controlled by the said relay switch solenoid coil 221. The closing of said normally closed relay switch contacts 305 completes a circuit thereacross by way of the wire or electrical conduit 252 for energizing electro-magnetic solenoid 306 and which controls the valve 268 for effecting a withdrawal of the elevator after, as pointed out above, it has discharged its said partial layer of filled containers onto the full layer of containers on the case bottom.

The limit switch 224 is mounted on the transverse frame member 302, see FIG. 1, however, on the under side of said transverse member wherefore it is below the limit switch 225. The said limit switch 224 is operated by the finger 295 which, as noted above, was adjusted at the same time the finger 292 was positioned for operation with filled containers of the pint capacity. It should be noted that while the limit switch 225 was operated on the first descent of the elevator with a full load it was at that time strapped out by the circuit including the relay switch contacts 286.

The limit switch 224 is in reality a double switch and includes the normally open limit switch 375 and which limit switch 375 is included in a bypass electric circuit or wire 376 which is strapped around the normally open relay switch contacts 276 which are controlled by the relay switch solenoid coil 275. The closing of said normally open relay switch 375 therefore completes a circuit through the said relay switch solenoid coil 275 which is by way of wire 274, wire 376 and the normally open now closed relay switch contacts 277 and the energization of which relay switch solenoid coil 275 closes the normally open relay switch contacts 276 for thereby establishing a holding circuit for the said relay switch solenoid coil 275.

As was noted above the machine or caser of the present invention is adapted for casing filled third quart containers and which is effected by depositing a first full layer on the bottom of the case and depositing a second full layer on top of the said first full layer. To accomplish this result it will further be appreciated that the elevator mechanism, as a whole, is adjusted for height through the handle or lever 373 since the third quart containers are of less height than the pint even though the width of the side walls are all substantially identical. The adjustment of the elevator mechanism carries with it the cam operating mechanism housing 285 and the parts carried thereby. The cam shafts 286 and 287 are also angularly adjusted with respect to one another whereby, when casing third quarts, the cams or fingers 293 and 296, respectively on shafts 286 and 287 are brought into operative positions for respectively actuating limit switches 225 and 224, the first switch 224 being operated when

the elevator reaches its lowest limit of travel for depositing the first full layer of filled containers on the case bottom and the second switch, 225, being operated by the finger 293 for releasing the second full layer of filled containers.

It will be appreciated that when casing third quart filled containers of two full layers that the case must remain clamped until the second layer is disposed in the case in the same way that when casing pints the case 10 must remain clamped until the second partial layer has been deposited.

In the casing of two full layers of filled containers, such as third quarts, the electric circuit in FIG. 7 is adjusted in that the manually operable switch 140 is closed while 15 the manually operable switch 160 is opened and the manually operable switch 272 remains open and the manually operable switch 279 remains closed as they were while casing half pint containers. The circuit is such now that the counting mechanism 199 will reset itself, 20 the movable 120, 121 and 122 will "home," after each fourth transfer of an accumulator load onto the carriage mechanism 84 and that the case will be released only after the eighth transfer or only after the second full carriage load and not after each full carriage load as with quart 25 size containers.

It is believed obvious from the foregoing that the operation of the upper limit switch 225 the first time will not release the case for the same reason that the case was not released when casing the lower or full layer of pint 30 size containers and that the operation of the lower layer limit switch 224 sets up the circuit so that the second operation of the upper layer limit switch 225 effects the case release.

As was noted above the machine is adapted to case 35 filled half pint containers and in which instance it is desirable to add a third layer of said filled containers to the case, with said third layer comprising either a half layer or a three-fourths layer, that is, eight or twelve filled half pint containers in said third layer. To adapt the machine 40 for the purpose of casing three layers of containers, in addition to casing one layer of quart size filled containers, or one full layer and a partial layer of pint size filled containers and two full layers of third quart size filled containers, a modification in the electrical equipment or circuit is required with substantially no change in the physical 45 components of the machine. The said modified machine is diagrammatically illustrated in FIG. 15.

In the first place a change is required in the rotary switch or counting mechanism 109 in that a fourth bank 50 of contacts is required along with a wiper or movable contact for homing the parts upon the completion of said third layer of filled pint containers.

Specifically the said fourth bank of contacts is identified in said FIG. 15 by reference numeral 377 and with 55 which cooperates movable contact 378 secured to and carried by the rotary switch shaft 119. The said movable contact 378 is connected with the control feed wire 135 by means of a strap or wire 379.

Connected with the bank fixed contacts 125 is a further 60 manually operable selector switch 380a including movable contact 380 connected by a wire 381 to contact No. 7 of said bank contacts 125. Said wire 381 and movable contact of switch 380a has a wire 382 extending therefrom and includes a manually operable selector switch 383 which is closed while casing half pint containers, and 65 which wire 382 terminates, in effect, in wire 159 ahead of selector switch 160, now open, and wherefore said wire 382 is ahead of the normally open solenoid switch contacts 156. The said bank contacts 125 has its contact 70 No. 9 connected by a wire 384 with one fixed contact 385 of said switch 380a, with said switch 380a having its second fixed contact 386 connected by a wire 387 with contact No. 10 of bank contacts 125.

From this it follows that upon the completion of the 75 second full layer on the carriage, that is, the eighth trans-

fer of half pints and with movable contact 122 on contact No. 7 of bank contacts 123 and the closing of counter switch 108 a circuit is completed through wire 148, movable contact 122, contact No. 7 of bank contacts 125, wires 381 and 382, normally open now closed contacts 150 for energizing solenoid coil 152 and thereby operating the carriage mechanism for positioning the said second full layer of filled half pint containers with respect to the grippers and which grippers and subsequent elevator operation is effected as above described.

It should be noted that in FIG. 15 the electro-magnet coil 116 is illustrated as a circle instead of as a part of the magnet for operating the armature and indicating mechanism; it is to be understood, however, that this mechanism is exactly as illustrated in FIG. 7 and is therefore an electro-magnet which not only operates contacts 150 but also operates contacts 267, the latter being normally closed though now open but which contacts, 267, will be closed as soon as the removable contact 122 moves away from contact No. 7 of bank contacts 125.

It should also be noted that in the circuit illustrated in FIG. 15 the solenoid switch coil 86 is illustrated as controlling normally closed switch contacts 88a and normally open switch contacts 89a, instead of a moveable switch contact such as 87 in FIG. 7. It is believed obvious, however, that the normally closed solenoid switch contacts 88a function the same as the moveable switch contact 87 and fixed contact 88 of FIG. 7, and also that the normally open solenoid switch contacts 89a function the same as the moveable switch contact 87 and fixed contact 89 of said FIG. 7. Also, in said FIG. 15, said solenoid coil 86 controls moveable solenoid switch contacts 105a which function the same as the moveable contact 103 and fixed contact 105 of FIG. 7.

With regard to control switch 380a and bank contacts 125 it will be noted that with said control switch 380a adjusted as illustrated in FIG. 15 that an additional half layer of filled half pint containers is to be added to the case being filled. This is accomplished upon the tenth transfer of filled half pint containers from the accumulator to the carriage whereupon with the movable contact 122 on contact No. 9 of bank contacts 125 and the closing of counter limit switch 108 and the energization of the electro-magnet coil 116 the electric circuit is completed through the wire 148, movable contact 122, contact No. 9 of bank contacts 125, wire 384, fixed and movable contacts 385 and 380 of control switch 380a, wire 382, selector switch 383, normally open now closed solenoid switch contacts 150 to and through solenoid switch coil 152 for again actuating the carriage to its position with respect to the container grippers and the lowering of the said half layer of filled containers into the case.

It is at this time that the fourth bank of contacts 377 come into play since the said bank of contacts has its contact No. 10 connected through a wire 388 with the movable contact 389 of a manually adjustable control switch 389a. Said control switch 389a has a fixed contact 390 thereof connected through the wire 139a with the wire 139, and said wire 139a including now closed manually operable selector switch 393 and wire 139a including the normally closed solenoid switch contacts 267, and which contacts are now closed for completing the electric circuit through the electro-magnet coil 116 and the wire 118 to the current rectifier 110. As noted above in connection with the homing bank contacts 124 the circuit just described operates the electro-magnet for advancing the rotary switch, in this instance but a single step, whereupon the movable contacts are home preparatory to recycling the machine, discharging a filled case and for filling an empty case.

It should be noted when the homing bank contacts 377 are employed the homing contact bank 124 is out of the circuit and for this purpose the control switch 141a has strapped there around a single throw selector switch 391 and a double throw selector switch 392-393 which

have their movable elements mechanically coupled with the switches 392 and 391 in the strap or wire 391a around the control switch 141a and with the switch 393 in the wire 139 closed while casing half pint containers as illustrated in FIG. 15; also at this time the selector switch 391 is illustrated as closed but since the switch 392 is open the closing of said selector switch 391 plays no part in the control of the machine at this time, it is for this reason that the homing contact bank 124 plays no part in the control of the circuit such as fully described above in the casing of quarts, pints and third quart containers.

In the event that the third layer in the case is to be a three-fourths layer rather than a half layer the movable contact 389, of control switch 389a, and the movable contact 380 of the control switch 380a are shifted to engage fixed contacts 394 and 386, respectively, of their control switches 389a and 380a; since the said movable contacts 389 and 380 are mechanically connected the shifting of one of them automatically shifts the other. As was noted above the said fixed contact 386 of the control switch 380a is connected by a wire 387 with contact No. 10 of bank contacts 125 and upon the eleventh transfer from the accumulator table to the carriage the circuit is complete for depositing said three-fourths third layer of half pint containers into the case. As will be noted from FIG. 15, the said second fixed contact 394 of control switch 389a is not electrically connected with anything and, in fact, need not so be since the opening 30 of the counter switch 108 for the eleventh time advances each of the movable contacts to its contact No. 11 of its bank of contacts and which is, as fully described above, the home or starting contact.

In the mechanism for operating the elevator mechanism 35 for supplying three layers of filled containers to a case it is desirable that a counting mechanism similar to the counting mechanism 109 of FIG. 7 be employed. Accordingly there is illustrated in FIG. 15 a counting mechanism which is mechanically substantially identical with 40 that disclosed in said FIG. 7 and the operating and ratchet parts thereof are identified by the same reference numerals with however the contacts and wiring being independently identified by reference numerals.

The counting mechanism 109" in FIG. 15, accordingly, 45 is provided with three banks of contacts 396, 397 and 398 respectively having associated therewith movable contacts 399, 400 and 401. The said banks of contacts and their movable contact member perform the same function as above, that is, the switch mechanism 396-399 being employed for resetting the counting switch prior to the first cycle of the machine, the switch mechanism 397-400 being employed for homing the mechanism after the placement of the third layer of filled containers in the case, and the switch mechanism 398-401 being 55 the control mechanism for operating or returning the elevator from the lower end of each of its strokes.

The control bank contacts 398 has the No. 1 contact thereof connected by a wire 402 with the wire 223 containing the limit switches 224 and 225 and with said 60 wire 223 further including normally closed limit switch 403 as well as normally open relay switch contacts 404 and with said wire 223 terminating in wire 218. Extending from said wire 223 is a wire 405 that terminates at opposite ends in the control circuit feed wires 78 and 79 65 with said wire 405 having disposed therein a control relay solenoid coil 406 as well as control relay normally open switch contacts 407.

In addition control bank contacts 398 has its No. 2 contact connected by a wire 408 with the aforementioned 70 wire 223 at a point, however, between limit switches 224 and 225 while the said wire 402 from contact No. 1 of bank contacts 398 terminates in said wire 223 at a point between limit switches 225 and 403.

In the circuit illustrated in FIG. 15 the limit switch 75 212 associated with and operated by the carriage mech-

nism in controlling the solenoid switch coil 215 also operates the elevator counter mechanism. For this reason the counter mechanism instead of including a mechanically operated limit switch 108, as above, includes a pair of normally open solenoid switch contacts 409 which are under the control of said solenoid coil 215 and are closed each time the gripper mechanism and the elevator mechanism are operated. The operation of the closing of the said solenoid switch contacts 409 is exactly the same as the operation of the limit switch 108, above, since it is included in the wire 114 which has connected therewith the wire 115 that terminates in one end of the solenoid coil 116 of electro-magnet 117. It is therefore obvious that each closing of limit switch 212 through the carriage mechanism advances the movable contacts 399, 400 and 401 of the elevator counting mechanism 109".

The energization of the solenoid coil 406, through the limit switch 212, also closes the normally open solenoid switch contacts 407 and simultaneously opens normally closed solenoid switch contacts 305 in wire 252. The opening of said solenoid switch contacts 305 breaks the circuit to the solenoid coil 306 while the closing of the solenoid switch contacts 404 completes the circuit to the solenoid coil 251 for causing the descent of the elevator to deposit the filled containers in the bottom of the empty case. The said circuit to the solenoid coil 251 is from the control circuit feed wire 78 through the wire 223 including normally closed, now closed, limit switches 224, 225 and 403, normally open, now closed, solenoid switch contacts 404, wire 218 including normally closed, now closed, solenoid switch contacts 254, normally open, now closed, solenoid switch contacts 253 and normally open, now closed, solenoid switch contacts 410, the said solenoid coil 251 and wire 252.

It should be here noted that solenoid switch contacts 410 takes the place of limit switch 250, above in FIG. 7, but that they serve the same purpose and are closed when the carriage return limit switch 83 is closed. For this purpose the said carriage return limit switch 83 is illustrated in FIG. 15 as in a separate circuit wire 411 extending from the control circuit feed wire 78 to the control circuit feed wire 79 with said wire 411 including a solenoid switch coil 412. The solenoid switch coil 412 controls the switch contacts 410 and since the carriage is fully retracted before the elevator descends the said solenoid switch contacts 410 are closed, as above set forth when the elevator control solenoid coil 251 is energized. The wire 80—82—85 of FIG. 7 from which said carriage return limit switch 83 was removed has in its place normally open solenoid switch contacts 413 which functions, in controlling the machine, in the same manner as said limit switch 83 in its circuit. The said solenoid switch contacts 413 are under the control of the solenoid switch coil 412 wherefore they are closed at this time.

The first descent of the elevator mechanism in casing filled half pint containers operates the limit switch 224 and thereby breaking its circuit and de-energizing the valve solenoid 251 and at the same de-energizing solenoid switch coil 406, opening solenoid switch contacts 404 and closing solenoid switch contacts 305. The closing of said switch contacts 305 energizes solenoid coil 306 for returning the said elevator to its uppermost position, as above set forth, and during which operation the second layer of filled half pint containers are being positioned on the carriage subsequent to disposition within the said case and on top of the first layer therein.

It will be appreciated that the limit switch 224 is, to all intents and purposes, the lowest of the control switch, 224, 225 and 403, that is, the elevator will travel the farthest to strike it, wherefore each of said switches 225 and 403 was operated, that is, opened, but nothing happened as they were rendered temporarily inoperative, as follows:

The operation of the counter switch mechanism 109"

upon commencement of this first descent of the elevator advanced the moveable contact 401 to contact No. 1 of bank contacts 398 and established a holding circuit from control circuit feed wire 78 through wire 414, manually operable selector switch 415, closed during the casing of half pint containers, and therefore shown as closed, wire 416, and which wire 416 is tapped to supply current to the rectifier 110 of counter mechanism 109", moveable contact 401, contact No. 1 of bank contacts 398 and wire 402 to the wire 223 at a point ahead of limit switches 225 and 403 but behind limit switch 224, and from which it follows that if either or both limit switch 225 and 224 were opened the elevator would continue to descend until the limit switch 224 is opened, as above described.

The opening of limit switch 224 breaks the circuit just traced and de-energizes the solenoid switch coil 406 and at the same time de-energizes the solenoid coil 251 of the valve 260. The de-energization of the solenoid switch coil 406 permitted the closing of normally closed solenoid switch contacts 305 and the energization of the solenoid coil 306 of the valve 260 for shifting said valve to the position thereof shown in the drawings and an upward movement of the elevator.

During the operation of the elevator the carriage was receiving its second full load of half pint containers, as above set forth and as soon as the carriage mechanism 84 has received its fourth transfer of said full load from the accumulator the said carriage mechanism is shifted 30 into operative position with and effects the operation of the gripper mechanism for again energizing the solenoid 251 for effecting the descent of the elevator to a position above the first layer of filled containers in the case whereupon the limit switch 225 is opened to break the circuit 35 to the control relay coil 406 and thereby open the circuit to the elevator lowering mechanism and effect the operation of the valve solenoid 306 for again retracting the elevator.

Again, it will be appreciated that the limit switch 403 40 was opened before the limit switch 225, but, again, the opening of switch 403 was rendered ineffective by the counter switch mechanism 109" because at the commencement of said second descent of the elevator the said counter switch mechanism 109" advanced the moveable contact 401 to contact No. 2 of bank contacts 398 and set up a holding or bypassing circuit from control circuit feed wire 78 through wire 414, selector switch 415, wire 416, moveable contact No. 2 of bank contacts 398 and wire 403 to the wire 223 at a point ahead of limit switch 224 but behind limit switches 225 and 403 and from which it follows that since limit switch 224 is not contacted it remains closed and the opening of limit switch 403 would not break the circuit the elevator will continue its descent until limit switch 225 is opened. 55 The opening of the limit switch 225 effects the release of the filled containers from the grippers and elevator return as above set forth in connection with the opening of said limit switch 224.

Again during the said retraction of the elevator the 60 second, this time, and, as noted above, a one-half or three-quarter layer of filled containers is being positioned on the carriage and upon the completion of which as determined by the counting mechanism 109' the elevator descends the third time and deposits the said third layer 65 of containers within the case. The third descent of the elevator opens limit switch 403 for again breaking the circuit to control relay solenoid coil 406 and opening the circuit to the solenoid 251 and completing the circuit to the solenoid 306 for retracting the elevator.

It should be noted that limit switch 225 is a double switch, the same as in the circuit disclosed in FIG. 7, and includes the normally open limit switch 307 which is closed upon the opening of said limit switch 225. The opening of said limit switch 307 in the circuit of FIG. 75 15 when casing half pint containers does not function

since its circuit line or wire 308 is broken by manually operable selector switch 430, subsequently to be referred to.

The limit switch 403 in FIG. 15 is similar to the limit switch 225, that is, is a double switch and includes limit switch 417 normally open but closed upon the opening of said limit switch 403 and functions in the casing of half pint containers in the same manner as limit switch 307 in the circuit of FIG. 7, that is, energizes the solenoid switch coil 310 for opening normally closed switch contacts 314 to de-energize solenoid 316 and effect the discharge of the filled case.

The limit switch 417 is in a wire 428 extending, in effect, from the wire 416 with said wire 428 including, on one side of the said limit switch 417, normally open switch contacts 428a and with said wire 428, on the other side of the limit switch 417, including a manually operable selector switch 427 closed during the casing of half pint filled containers and which selector switch 427 is so illustrated in FIG. 15.

The normally open switch contacts 428a, are known in the trade as "off normal" contacts, and are illustrated in FIG. 15 as associated with or operated by the electro-magnet 117 but actually said switch contacts are closed by a cam (not shown) on the counter mechanism shaft 119, of the counter mechanism 109", and are closed only when the movable contacts 399, 400 and 401 are in their "home" positions as illustrated in the drawings. From this it follows that when the switch 417 is closed upon the opening of limit switch 403, in placing the third layer of half pint containers in the case, the circuit to the solenoid coil 310 is from wire 78 through wire 414, manually operable selector switch 415, wires 416 and 428, limit switch 417, manually operable selector switch 427 and wire 308 to and through the said solenoid coil 310.

It will be understood that each time the gripper mechanism operated for energizing relay switch solenoid coil 215 the counting contacts 409 were closed for energizing the electro-magnet solenoid coil and thereby advancing the movable contacts 399, 400 and 401 of counter mechanism 109". With the wiring circuit as illustrated in FIG. 15 the said movable contact 400 is now on contact No. 3 of bank contacts 397 and which contact No. 3 has extending therefrom a wire 418 which terminates in contact No. 2 of said bank contacts 397 and with said wire 418 having therein a manually operated selector switch 419 which is open during the casing of half pint filled containers. The said wire 418 has extending therefrom beyond said manually operable switch 419 a wire 420 that terminates in a wire 139 which in turn includes normally closed solenoid switch contacts 267 and with said wire 139 terminating in the wire 115, and therefore one end of electro-magnet coil 116. The contacts numbered 3 to 10 of bank contacts 397 are bridged or connected with one another by a wire 421 and therefore with the wires 418, 420, 139 and 115 with the said electro-magnet coil 116 through the normally closed solenoid switch contacts 267. From this it follows that as soon as the elevator has effected its third descent the counting mechanism 109" is automatically reset for a new cycle.

The bank contacts 396 similar to the bank contacts 123, above, are connected to the end of the wire 139 for the purpose of resetting the counting mechanism 109" prior to the starting of the machine in the event that the machine had been shut down with the movable contacts of the counting mechanism 109" on a contact other than the home contact.

The resetting or "homing" bank contacts 396 receive current from the movable contact 399 which in turn is connected through a wire 422 with the wire 268 of movable contact 120 so that the same manually operable resetting switch 269 may be employed for resetting both counting mechanisms 109' and 109". It will be noted that the wire 422 includes a pair of normally open con-

tacts 423, these contacts being similar to contacts 428a, above, and "off normal," and are mechanically closed by a cam on the counter mechanism shaft 119 of counter mechanism 109' when the rotary switch 109' is on the 5 home position and is a part of the said counter mechanism as supplied by the manufacturer, above set forth, and is employed to sequentially reset counter mechanisms 109' and 109" in order that the drain on the rectifier 110 of said counter switch is not being used 10 to simultaneously reset both counter mechanisms.

It will be obvious from FIG. 1 that the positions of the limit switches 224, 225 and 403 with respect to the travel of the elevator mechanism and the positions of the several cams or fingers on the shafts 286 and 287 15 cause the release of the containers at different elevations with respect to the bottom of the case, namely, the operation of the limit switch 224 by the fingers on the shaft 286 will take place lower in the case, in fact, substantially at the bottom of the case, and will therefore be 20 at the end of a greater travel of the elevator, while the operation of the limit switch 225 by the cam fingers on the shaft 287 is effected at a considerably higher point and which point is variable since the said containers, pints and third quarts are of progressively less height. Similarly the three layers of half pint containers are released 25 at various heights above the case bottom with said lower-most layer and middle layer operated by fingers or cams on said shafts 286 and 287, while the third or uppermost layer thereof is preferably released by a fixed cam or 30 finger 424 carried by the said shaft's housing.

While the control mechanism illustrated in FIG. 7 has been described for controlling the casing of either a single layer of filled containers, such as quarts, or a full layer and a second partial layer, such as pints and two full 35 layers such as third quarts, and the control mechanism as illustrated in FIG. 15 as casing half pint containers in which two full layers and a third partial layer of said containers are disposed in a case; it should be noted that the control mechanism in FIG. 15 can be readily adjusted 40 for accomplishing the same results as accomplished by the mechanism of FIG. 7 and this is accomplished by the adjustment of various manually operable switches as follows:

If it is desired to case two full layers such as third quart 45 containers the manually operable selector switch 383 is open, the selector switch 160 is open, the selector switch 391 is closed, the selector switch 392 is closed, the selector switch 393 is open, the selector switch 425, in a wire 426 extending from the control circuit feed wire 78 and terminating in wire 223 at a point between limit switches 50 403 and 225, is closed (this is for the purpose of strapping out limit switch 403 on the first descent of the elevator), the selector switch 419 is closed, the selector switch 427, in a wire 428 which includes limit switch 417 and extends 55 from the tap in wire 416 and therefore from control circuit feed wire 78 to the wire 308 at a point ahead of the solenoid switch coil 310 (said limit switch 417 is mechanically coupled with limit switch 403, as noted above, and therefore not used) is open, manually operable selector switch 415 is closed, and manually operable switch 60 430, in the wire 308, is open.

If it is desired to case one full layer and one partial layer such as pint containers the manually operable selector switches in FIG. 15 are arranged as follows, the 65 manually operable selector switch 383 is open, the selector switch 160 is closed, the selector switch 391 is open, the selector switch 392 is closed, the selector switch 393 is open, the selector switch 425 is closed, the selector switch 419 is closed, the selector switch 427 is open, the selector switch 415 is closed, and the manually operable selector switch 430 is open.

It is believed, in view of the foregoing description of the control circuits in said FIGS. 7 and 15 that the operation of the circuit with the above indicated positioning 70 of the manually selectable switches will be obvious.

It should be noted that when casing pint and third quart size containers, that is, two layers of containers, whether both layers are full or only one full layer and the other a partial layer, the case must remain clamped in position until said second layer is cased but must then be released. The case releasing mechanism includes the solenoid switch coil 310, operated, as above, by the closing of limit switches 417 and 307, but since limit switch 417 is rendered inoperative by the opening of manually operated selector switch 427 the closing of said limit switch 417 upon the opening of limit switch 403 upon the placement of the first layer in the case the said solenoid switch coil 310 remains de-energized.

In order to energize said solenoid switch coil 310 the wire 428 and the wire 308 are connected by a strap wire 307a located in wire 428 at a point between "off normal" contacts 428a and limit switch 417 with said strap wire 307a located in the wire 308 at a point ahead of limit switch 307. Upon the casing of said second layer the counting mechanism 109' resets itself and upon the homing of the movable contacts 399, 400 and 401 the "off normal" contacts 428a are closed, as above set forth, so that the closing of the limit switch 307 upon the opening of upper layer releasing limit switch 225 establishes an electric circuit as follows:

From the control circuit current wire 78 through wire 414, closed manually operable selector switch 415, wires 416 and 428, closed "off normal" contacts 428a, strap wire 307a, wire 308 and limit switch 307 to solenoid switch coil 310 and control circuit current wire 79.

When it is desired to case but a single layer of filled containers on the bottom of the case, as when casing filled quart size containers, the said manually selectable switches in FIG. 15 are arranged as follows:

Manually operable selector switch 383 is open, manually operable selector switch 160 is open, manually operable selector switch 391 is closed, manually operable selector switch 392 is closed, manually operable selector switch 393 is open, manually operable selector switch 425 is closed, manually operable selector switch 419 is closed, manually operable selector switch 427 is open, manually operable selector switch 415 is open and manually operable selector switch 430 is closed. Again, it is believed, that the operation of the control circuit is obvious from the foregoing description of the circuits.

As was noted above there is incorporated in each of the control circuits an alarm mechanism which includes the contacts or switch portion 50 of the double switch 49-50 and of which the contacts or switch portion 49 is operated upon accumulation of the desired number of filled containers on the accumulator table. This alarm mechanism includes, as noted above, the switch portion 50 in a wire 431 extending from the control circuit feed wire 79 to the wire 256 at a point behind the limit switch 257 and which limit switch, as noted above, is closed upon the positioning of an empty case to receive filled containers. Included in the wire 431 is a solenoid coil 432 which operates a normally closed switch 433. The switch 433 is an adjustable self acting switch including a time delay wherefore it operates only after a given time period after the energization of the said solenoid coil 432.

The time delay switch 433 is in a wire 434 having its opposite ends respectively connected with the control circuit feed wires 78 and 79 and with said wire 434 including a manually operable "on and off" switch 435 as well as an alarm giving device such as the audible alarm diagrammatically illustrated at 436 in said FIGS. 7 and 15.

The operation of the alarm is such, that, if after the discharge of a filled case an unusual amount of time elapses before an empty case is positioned to close the limit switch 257, the alarm will sound since the solenoid coil 432 being de-energized permits the time delay switch 433 to close and therefor sound the alarm 436. It is to be understood that this time delay is measured in seconds

as the rate of filling the containers and the casing thereof is quite rapid.

From the foregoing it will now be appreciated that there has been provided a control and operating mechanism for a machine for placing containers in a box, basket or case and said container placement consisting either of a single layer on the case bottom with a partial layer on said case bottom layer, or a second full layer on the case bottom layer or two full layers and a third partial layer on said second full layer. It will further be noted that the said containers are continuously supplied to the casing machine and counted for delivery to a case and that said containers are accumulated in a proper or desirable order whereupon they are transferred to a carriage mechanism. The carriage mechanism is retained in position for receiving the accumulated containers until the desired number of containers, enough to make a full layer, or enough to make a desired partial layer, or enough to make two full layers and a partial layer, are received whereupon the carriage mechanism moves said containers to a position to be gripped or picked up by an elevator mechanism, said carriage itself elevating the containers to the proper position with respect to the elevator gripper or pick up device. The gripper or pick up device after properly gripping the containers permits the carriage mechanism to return to its receiving station whereupon the elevator lowers the containers to the case. The case is in a fixed or clamped position with respect to the elevator and so remains until the desired number of filled containers, whether a single layer, a single and a partial layer, two full layers or a double layer plus a partial layer is counted and delivered thereto whereupon the case with its contents is released for replacement by an empty case.

It will further be noted that various steps in the travel of the filled containers, namely, from the accumulator to the carriage, the carriage to the gripper, the gripper to the case, and the replacement of the case, are all interlocked so that no subsequent operation is effected until the completion of the preceding operation.

Any suitable or desirable means may be employed in positioning and clamping an empty case with respect to the elevator and for automatically subsequently releasing the said case with its contents. As noted above in connection with the case pneumatic control circuit in FIG. 9 these functions are accomplished through piston and cylinder mechanisms. A physical embodiment of such a device is illustrated in FIGS. 1 and 2 and may include the following mechanism.

The cases are adapted to be transferred from a supply source exteriorly of the machine and which may be a decontaminating operation by a supplemental conveyor mechanism 258, referred to above, and which comprises a supporting frame work 437 on which is mounted a conveyor chain 438 conventional in all respects and well known. Mounted on a supplemental frame 439 immediately below the conveyor mechanism is the limit switch 257 which is provided with a movable or rotatable actuator 440 having a contact member 441 to be engaged by the forward or leading edge of the case 259. The case after engaging and operating the relay switch actuator engages a fixed stop 350. Mounted on a second portion of the supplemental frame 439 is a lever 443 having at its upper end an ejector and clamp shoe 349. The ejector shoe 349 is positioned to cooperate with a clamp shoe and eject at the proper or desired point with respect to the elevator upon its being withdrawn, as above pointed out in connection with the case positioning and clamping mechanism. As will be noted in FIGS. 1 and 2 the lever 443 is pivoted at 445 and has its lower end pivotally connected with the piston 346 of the cylinder 344.

During the holding of the case 259 by the stop 350 it is clamped in position and securely held until released by mechanism quite similar to the ejector mechanism. The clamping mechanism includes an arm or lever 446

pivoted intermediate its ends at 447 to the supplemental frame 439 and having at its upper end a clamp shoe 348. The lower end of the lever 446 is connected with the piston rod 331 of the clamp cylinder 329.

As shown in FIG. 1 the cylinders 329 and 344 are mounted through a similar bracket 449 to the supplemental frame 439 preferably substantially centrally of said supplemental frame to operate in opposite directions. It will be understood that the clamping of the case 259 is through the clamp shoe 348 holding the case against the opposite side of the conveyer mechanism and particularly against the clamping pad or against the ejector shoe 349.

As shown in FIG. 1 a conveyer mechanism 450 is provided to the left of the conveyer mechanism 438 and which may be employed for empty cases to be subsequently transferred to the said conveyer mechanism 438 for placement and positioning with respect to the caser elevating mechanism. A similar conveyer mechanism 451 is provided to the right of the conveyer mechanism 437 and to which the filled cases are transferred after release from the caser.

It will be noted that the conveyer mechanism 450 is below the mechanism which accumulates the filled containers and the transfer mechanism which shifts or transfers the accumulated containers to the carriage and elevator mechanisms, while the conveyer mechanisms 451 is mounted beneath the control mechanism which includes the hydraulic valves and their operating electro-magnetic solenoids which effect and control the operation of the transfer mechanism, the carriage mechanism and the elevator mechanism.

As seen in FIGS. 1 and 3 said control valves and their respective operating electro-magnetic solenoids are mounted on a suitable transverse supporting structure 452 at the upper end of the outermost vertical frame member 28. It should be noted that adjacent to the said supporting frame 452 the machine frame supports a platform 453 which is the operator's station for operating the control cam shafts 286 and 287 and for actuating the handle or lever 373 in adjusting the elevator mechanism depending upon the size or capacity of containers being cased.

Disposed above the frame 452 and platform 453 on the right hand side of the machine uprights is disposed a cabinet 454 closed by an access door 455 and which cabinet houses the various relay switches solenoid coils and their control contacts as well as other control mechanism utilized in the electric control circuit and above pointed out as well as the switches for starting and stopping the hydraulic pump motor and the filled containers' conveyer motor.

The motor operating and control circuit source disclosed in FIG. 10 is believed self-explanatory but in brief comprises the three wire current source 456 which enters a magnetic starting switch 457 and which starting switch is under the control of a manual starting switch 458 located adjacent the hydraulic unit as well as under the control of a second manual starting switch 459 which may be remote from the hydraulic unit. Associated with each control switch 458 and 459 is a stop switch 460 and 461. Extending from the electro-magnetic switch 457 are the wires 462 to the hydraulic pump motor 463.

The complete circuit to and through the electro-magnetic switch 457 upon closing of either of the starting switches 458 and 459 is from one of wires 456 through wire 464, stop switch 461, wire 465, which ever of said starting switches is closed, either of wires 466 and 457, wire 468, wire 469, solenoid coil 470 and wire 471 to the second of the wires of the source 456.

Extending from two of the main current source wires 456 are wires 472 and 473 which are connected with the coil 474 of a current transformer and which current transformer has connected with its secondary coil 475, wires 476 and 477 which after passing through control

starting switch 478 and stopping switch 479 feed the control circuit feed wires 78 and 79. Included with the control switches 478 and 479 is a relay switch solenoid coil 480 controlling normally open relay switch contacts 481 and 482 and which maintain the solenoid coil 480 energized upon opening of switch 478. Suitable indicators 483 and 484 are also included in the hydraulic motor operating circuit and the control current lines.

Mounted in the wire 477 is a pressure switch 485 which breaks the circuit if insufficient pressure occurs in the pressure source and main air line 241—319.

What is claimed is:

1. In a caser of the class described the combination
15 of an accumulator table receiving and accumulating a
capacity of a given number of filled containers, a normally
stationary carriage ahead of the accumulator table of a
capacity greater than the capacity of the accumulator
table, means operable by said containers after each
20 accumulator table accumulated capacity for effecting
transfer of said accumulator table capacity number of
containers onto said stationary carriage, means shifting said
carriage from its normal stationary position after the
transfer thereto of a predetermined number of successive
25 transfers of containers, control means for said carriage
shifting means, a counting mechanism operable by said
transfer means counting the number of successive transfers
to the carriage from the accumulator table, and
means operable by said counting mechanism after the
30 reception by said carriage of the predetermined number
of transfers operating said carriage shifting control means.

2. In a caser of the class described the combination
of an accumulator table receiving and accumulating a
capacity of a given number of filled containers, a normally
stationary carriage ahead of the accumulator table
35 of a capacity greater than the capacity of the accumulator
table, means operable by said containers after each
accumulator table accumulated capacity for effecting
transfer of said accumulator table capacity number
40 of containers onto said stationary carriage, means shifting
said carriage from its normal stationary position after
the transfer thereto of a predetermined number of successive
transfers of containers, and returning the carriage
45 to its normal stationary position, control means for said
carriage shifting means, a counting mechanism operable
by said transfer means counting the number of successive
transfers to the carriage from the accumulator table,
means operable by said counting mechanism after the
50 reception by said carriage of a predetermined number
of transfers operating said carriage shifting control means,
means removing said containers from the carriage after
the shifting thereof from its normal stationary position,
and means operable by the containers removing means
55 for actuating the carriage shifting control means returning
the carriage to its normal stationary position.

3. In a caser of the class described the combination
of an accumulator table receiving and accumulating a
capacity of a given number of filled containers, a normally
stationary carriage ahead of the accumulator table of a
60 capacity greater than the capacity of the accumulator
table, means operable by said containers after each ac-
cumulator table accumulated capacity for effecting trans-
fer of said accumulator table capacity number of con-
tainers onto said stationary carriage, means shifting said
65 carriage from its normal stationary position after the
transfer thereto of a predetermined number of successive
transfers of containers and returning the carriage to its
normal stationary position, control means for said car-
riage shifting means, a counting mechanism operable by
70 said transfer means counting the number of successive
transfers to the carriage from the accumulator table,
means operable by said counting mechanism after the
reception by said carriage of a predetermined number
of transfers operating said carriage shifting control means,
means removing said containers from the carriage after
75 the shifting thereof from its normal stationary position,

means operable by the containers removing means for actuating the carriage shifting control means returning the carriage to its normal stationary position, and means resetting the counting mechanism during the removal of the containers from the carriage and the return of the carriage to its normal stationary position.

4. In a case of the class described the combination of an accumulator table receiving and accumulating a capacity of a given number of filled containers, a normally stationary carriage ahead of the accumulator table of a capacity greater than the capacity of the accumulator table, means operable by said containers after each accumulator table accumulated capacity for effecting transfer of said accumulator table capacity number of containers onto said stationary carriage, means shifting said carriage from its normal stationary position after the transfer thereto of a predetermined number of successive transfers of containers and returning the carriage to its normal stationary position, control means including electro-magnetic means for said carriage shifting means, a counting mechanism including a rotary electric switch operable by said transfer means counting the number of successive transfers to the carriage from the accumulator table, said rotary electric switch being adapted to be incrementally rotated, one increment of rotation upon each transfer of accumulated containers to the carriage, and means operable by said rotary switch after a definite number of incremental rotations thereof operating said carriage shifting electro-magnetic control means.

5. In a case of the class described the combination of an accumulator table receiving and accumulating a capacity of a given number of filled containers, a normally stationary carriage ahead of the accumulator table of a capacity greater than the capacity of the accumulator table, means operable by said containers after each accumulator table accumulated capacity for effecting transfer of said accumulator table capacity number of containers onto said stationary carriage, means shifting said carriage from its normal stationary position after the transfer thereto of a predetermined number of successive transfers of containers and returning the carriage to its normal stationary position, control means including electro-magnetic means for said carriage shifting means, a counting mechanism including a rotary electric switch operable by said transfer means counting the number of successive transfers to the carriage from the accumulator table, said rotary electric switch being adapted to be incrementally rotated, one increment of rotation upon each transfer of accumulated containers to the carriage, means operable by said rotary switch after a definite number of incremental rotations thereof operating said carriage shifting electro-magnetic control means, means removing said containers from the carriage after the shifting thereof from its normal stationary position, and means operable by the containers removing means for actuating the carriage shifting control means returning the carriage to its normal stationary position.

6. In a case of the class described the combination of an accumulator table receiving and accumulating a capacity of a given number of filled containers, a normally stationary carriage ahead of the accumulator table of a capacity greater than the capacity of the accumulator table, means operable by said containers after each accumulator table accumulated capacity for effecting transfer of said accumulator table capacity number of containers onto said stationary carriage, means shifting said carriage from its normal stationary position after the transfer thereto of a predetermined number of successive transfers of containers and returning the carriage to its normal stationary position, control means including electro-magnetic means for said carriage shifting means, a counting mechanism including a rotary electric switch operable by said transfer means counting the number of successive transfers to the carriage from the accumulator table, said rotary electric switch being adapted to be in-

crementally rotated, one increment of rotation upon each transfer of accumulated containers to the carriage, means operable by said rotary switch after a definite number of incremental rotations thereof operating said carriage shifting electro-magnetic control means, means removing said containers from the carriage after the shifting thereof from its normal stationary position, means operable by the containers removing means for actuating the carriage shifting control means returning the carriage to its normally stationary position, and means further incrementally rotating the rotary electric switch and resetting the counting mechanism during the removal of the containers from the carriage and the return of the carriage to its normally stationary position.

7. In a case of the class described the combination of an accumulator table receiving and accumulating a capacity of a given number of filled containers, a normally stationary carriage ahead of the accumulator table of a capacity greater than the capacity of the accumulator table, means locating and supporting a case laterally of the carriage normal stationary position and adapted to receive the containers in layers above one another, means operable by said containers after each accumulator table accumulated capacity for effecting transfer of said accumulator table capacity number of containers onto said stationary carriage, means shifting said carriage from its normal stationary position to a position laterally thereof and over the case after the reception thereby of a predetermined number of successive transfers of containers and returning the carriage to its normal stationary position, control means for said carriage shifting means, a counting mechanism operable by said transfer means counting the number of successive transfers to the carriage from the accumulator table for first counting and determining the number of transfers to the carriage which forms the lower layer of containers in the case and subsequently counting the transfers to the carriage which forms the upper layer of containers in the case, and means operable by said counting mechanism after each determination thereby that the carriage has had the desired number of transfers thereto to provide a layer of containers for the case and operating said carriage shifting control means, and means removing the containers from the carriage after each lateral shifting thereof.

8. In a case of the class described the combination of an accumulator table receiving and accumulating a capacity of a given number of filled containers, a normally stationary carriage ahead of the accumulator table of a capacity greater than the capacity of the accumulator table, means locating and supporting a case laterally of the carriage normal stationary position and adapted to receive the containers in layers above one another, means operable by said containers after each accumulator table accumulated capacity for effecting transfer of said accumulator table capacity number of containers onto said stationary carriage, means shifting said carriage from its normal stationary position to a position laterally thereof and over the case after the reception thereby of a predetermined number of successive transfers of containers and returning the carriage to its normal stationary position, control means for said carriage shifting means, a counting mechanism operable by said transfer means counting the number of successive transfers to the carriage from the accumulator table for first counting and determining the number of transfers to the carriage which forms the lower layer of containers in the case and subsequently counting the transfers to the carriage which forms the upper layer of containers in the case, means operable by said counting mechanism after each determination thereby that the carriage has had the desired number of transfers thereto to provide a layer of containers for the case and operating said carriage shifting control means, means removing the containers from the carriage after each lateral shifting thereof, means operable by the containers removing means for actuating the

carriage shifting control means returning the carriage to its normal stationary position, and means operable after the final transfer to the carriage to form the case upper level resetting the counting mechanism during the removal of the containers from the carriage that form said upper level and the return of the carriage to its normal stationary position.

9. In a caser of the class described the combination of an accumulator table receiving and accumulating a capacity of a given number of filled containers, a carriage ahead of the accumulator table of a capacity greater than the capacity of the accumulator table, means locating and supporting a case laterally of the carriage adapted to receive the containers in batch layers one above the other and with each layer having a predetermined number of containers, transfer means operable by said containers after each accumulation of a capacity number on the accumulator table transferring said containers to said carriage, a counting mechanism operable by the transfer means counting each transfer of said containers from the accumulator table to the carriage and determining a batch layer thereof, means including control means removing said batch layer of containers from the carriage to the case and operable after the transfer to the carriage of containers sufficient to form a batch layer thereof, and means operable by the counting mechanism after the transfer to the carriage of sufficient containers to form a batch layer for operating said control means of the container removing means.

10. In a caser of the class described the combination of an accumulator table receiving and accumulating a capacity of a given number of filled containers, a carriage ahead of the accumulator table of a capacity greater than the capacity of the accumulator table, means locating and supporting a case laterally of the carriage adapted to receive the containers in batch layers one above the other and with each layer having a predetermined number of containers, transfer means operable by said containers after each accumulation of a capacity number on the accumulator table transferring said containers to said carriage, a counting mechanism operable by the transfer means counting each transfer of said containers from the accumulator table to the carriage and determining a batch layer thereof, means including control means removing said batch layer of containers from the carriage to the case and operable after the transfer to the carriage of containers sufficient to form a batch layer thereof, means operable by the counting mechanism after the transfer to the carriage of sufficient containers to form a batch layer for operating said control means of the container removing means, and counting means operable by said containers removing means for rendering its control means inoperative after the desired number of batch layers are in the case.

11. In a caser of the class described the combination of an accumulator table receiving and accumulating a capacity of a given number of filled containers, a carriage ahead of the accumulator table of a capacity greater than the capacity of the accumulator table, means locating and clamping a case in position laterally of the carriage adapted to receive the containers in batch layers one above the other and with each layer having a predetermined number of containers, transfer means operable by said containers after each accumulation of a capacity number on the accumulator table transferring said containers to said carriage, a counting mechanism operable by the transfer means counting each transfer of said containers from the accumulator table to the carriage and determining a batch layer thereof, means including control means removing said batch layer of containers from the carriage to the case and operable after the transfer to the carriage of containers sufficient to form a batch layer thereof, means operable by the counting mechanism after the transfer to the carriage of sufficient containers to form a batch layer for operating said control means

of the container removing means, counting means operable by said containers removing means for rendering its control means inoperative after the desired number of batch layers are in the case, means clamping the case in operative position during the placement of containers therein, and means operable by the containers removing means for unclamping the case after the desired number of batch layers are placed therein.

12. In a caser of the class described the combination

10 of an accumulator table receiving and accumulating a capacity of a given number of filled containers, a normally stationary carriage ahead of the accumulator table of a capacity greater than the capacity of the accumulator table, means locating and supporting a case laterally of the carriage normal stationary position and adapted

15 to receive the containers in batch layers one above the other and with each layer having a predetermined number of containers, transfer means operable by said containers after each accumulation of said capacity number thereof on the accumulator table transferring same to said carriage, a first counting mechanism operable by the transfer means counting each transfer of said containers from the accumulator table to the carriage and determining a batch layer thereof, means shifting said

20 carriage from its normal stationary position to a position laterally thereof above the case, means operable by said first counting mechanism operating said carriage shifting means, means including a vertically reciprocal member removing the containers from the carriage to the case in

25 layer batches as determined by the counting mechanism, a second counting mechanism counting each vertical reciprocation of the vertically reciprocal member and therefor each layer batch of containers deposited in the case, and means operable by said second counting mechanism rendering the vertically reciprocal member shifting means inoperative after a predetermined number of vertical reciprocations of the containers removing means.

13. In a caser of the class described the combination

30 of an accumulator table receiving and accumulating a capacity of a given number of filled containers, a normally stationary carriage ahead of the accumulator table of a capacity greater than the capacity of the accumulator table, means locating and supporting a case laterally of the carriage normal stationary position and adapted

35 to receive the containers in batch layers one above the other and with each layer having a predetermined number of containers, transfer means operable by said containers after each accumulation of said capacity number thereof on the accumulator table transferring same to said carriage, a first counting mechanism operable by the transfer means counting each transfer of said containers from the accumulator table to the carriage and determining a batch layer thereof, means shifting said

40 carriage from its normal stationary position to a position laterally thereof above the case, means operable by said first counting mechanism operating said carriage shifting means, means including a vertically reciprocal member removing the containers from the carriage to the case in layer batches as determined by the counting mechanism,

45 a second counting mechanism counting each vertical reciprocation of the vertically reciprocal member and therefor each layer batch of containers deposited in the case, means operable by said second counting mechanism rendering the vertically reciprocal member shifting means inoperative after a predetermined number of vertical reciprocations of the containers removing means,

50 said case locating and supporting means including means clamping said case in operative position, and means rendering said clamping means inoperative after the placement of said given number of layer batches in the case as determined by the said second counting mechanism.

14. In a caser of the class described the combination

55 of an accumulator table receiving and accumulating a capacity of a given number of filled containers, a normally stationary carriage ahead of the accumulator table

of a capacity greater than the capacity of the accumulator table, means locating and supporting a case laterally of the carriage normal stationary position and adapted to receive the containers in batch layers one above the other and with each layer having a predetermined number of containers, transfer means operable by said containers after each accumulation of said capacity number thereof on the accumulator table transferring same to said carriage, a first counting mechanism operable by the transfer means counting each transfer of said containers from the accumulator table to the carriage until a layer batch thereof has been transferred to the carriage, means shifting said carriage from its normal stationary position to a position laterally thereof and above the case, means operable by said first counting mechanism operating said carriage shifting means, means including a vertically reciprocal member removing the containers from the carriage to the case in layer batches as determined by the counting mechanism, a second counting mechanism counting each vertical reciprocation of the vertically reciprocal member and thereof each layer batch of containers deposited in the case, means operable by said second counting mechanism rendering the vertically reciprocal member shifting means inoperative after a predetermined number of vertical reciprocations of the containers removing means, said case locating and supporting means including means clamping said case in operative position, means rendering said clamping means inoperative after the placement of said given number of layer batches in the case as determined by the said second counting mechanism, and means resetting each of said counting means after placement of said given number of layer batches of containers in the case.

15. In a caser of the class described for placing a predetermined number of layers of filled containers in a case, the combination of a carriage in a normally stationary loading position and adapted to receive a plurality of filled containers with said containers arranged on said carriage to form a case layer, means determining when said containers on the carriage constitute a case layer, means mounting said carriage for lateral movement from its loading position to an unloading position, means actuating the carriage from its loading to its unloading position, means operable to remove said containers while in said case layer arrangement from the carriage when in its unloading position and place same in the carriage, and a counting mechanism operated by the carriage in its unloading position and counting the number of lateral movements of the carriage to determine when the desired number of layers of containers has been placed in the case.

16. In a caser of the class described for placing a predetermined number of layers of filled containers in a case, the combination of a carriage in a normally stationary loading position and adapted to receive a plurality of filled containers with said containers arranged on said carriage to form a case layer, means determining when said containers on the carriage constitute a case layer, means mounting said carriage for lateral movement from its loading position to an unloading position, means actuating the carriage from its loading to its unloading position, means operable to remove said containers while in said case layer arrangement from the carriage when in its unloading position and place same in the carriage, a counting mechanism operated by the carriage in its unloading position and counting the number of lateral movements of the carriage to determine when the desired number of layers of containers has been placed in the case, means supporting and clamping the case in position during the placement of the containers therein, and means

rendering said case clamping means inoperative after the placement therein of a predetermined number of container layers as determined by the counting mechanism.

17. In a caser of the class described for placing a predetermined number of layers of filled containers in a case, the combination of a carriage in a normally stationary loading position and adapted to receive a plurality of filled containers with said containers arranged on said carriage to form a case layer, means determining when said containers on the carriage constitute a case layer, means mounting said carriage for lateral movement from its loading position to an unloading position, means actuating the carriage from its loading to its unloading position, means operable to remove said containers while in said case layer arrangement from the carriage when in its unloading position and place same in the carriage, a counting mechanism operated by the carriage in its unloading position and counting the number of lateral movements of the carriage to determine when the desired number of layers of containers has been placed in the case, said counting mechanism including a rotary electric switch operable by said carriage upon movement thereof to its unloading position, said rotary switch being adapted to be incrementally rotated one increment of rotation for each operation of the carriage, means supporting and clamping the case in position during the placement of the containers therein, and means operable by said rotary switch after a definite number of incremental rotations thereof corresponding to the predetermined number of layers of containers in the case for rendering the case clamping means inoperative.

18. In a caser of the class described for placing a predetermined number of layers of filled containers in a case, the combination of a carriage in a normally stationary loading position and adapted to receive a plurality of filled containers with said containers arranged on said carriage to form a case layer, means determining when said containers on the carriage constitute a case layer, means mounting said carriage for lateral movement from its loading position to an unloading position, means actuating the carriage from its loading to its unloading position, means operable to remove said containers while in said case layer arrangement from the carriage when in its unloading position and place same in the carriage, a counting mechanism operated by the carriage in its unloading position and counting the number of lateral movements of the carriage to determine when the desired number of layers of containers has been placed in the case, said counting mechanism including a rotary electric switch operable by said carriage upon movement thereof to its unloading position, said rotary switch being adapted to be incrementally rotated one increment of rotation for each operation of the carriage, means supporting and clamping the case in position during the placement of the containers therein, means operable by said rotary switch after a definite number of incremental rotations thereof corresponding to the predetermined number of layers of containers in the case for rendering the case clamping means inoperative, and means further incrementally rotating the rotary electric switch and resetting the counting mechanism after its operation for rendering the case clamping means inoperative.
